AUTOMATIC TELEPHONE SYSTEM

Hans P. Boswau, Lorain, Ohio

Application November 30, 1939, Serial No. 306,929

55 Claims. (Cl. 179—25)

The present invention relates in general to automatic telephone systems, and the object of the invention is to produce a new and improved system of this character, which is economical to manufacture, easy to install, and which will give service of high grade with a minimum of maintenance expense.

A special object of the invention is the production of a new and improved switching mechanism for use in automatic telephone systems.

The invention and various features of improvement comprised therein will be described hereinafter in connection with the accompanying drawings, in which:

Fig. 1 is a partial side view of a single unit of switching equipment;

Fig. 2 is a section on the line 2—2, Fig. 1, drawn to a somewhat larger scale;

Fig. 3 is a top view of the switching unit shown in Figs. 1 and 2, with certain parts broken away;

Figs. 4 to 7, inclusive, are views which show details of the supporting means for certain of the operating bars;

Fig. 8 shows one of the link operating members;

Fig. 9 is a fragmentary view of a switching unit in perspective, intended to facilitate an understanding of the principles on which it operates;

Fig. 10 is an exploded view of a part of the bank, showing the construction of the contact members and insulators; while

Figs. 11 to 14, inclusive, show circuit drawings of a complete automatic telephone system using switching units of the type disclosed herein.

Referring now to Figs. 1 to 10, inclusive, the switching unit which is shown in these views will first be described.

The various parts of the unit are mounted on a frame which comprises vertical end members 1 and 2, of angle iron, and top and bottom members 3 and 4. The top member 3 is a flat metal plate having upturned end 5, Fig. 1, which is secured to the vertical member 1 by screws, as shown. The opposite end is similarly upturned and is secured to the vertical member 2. The member 3 is also provided with upturned side flanges 6 and 7. The bottom member 4 is similar to member 3 and is provided with downturned ends 10 and 11 which are secured to the vertical members 1 and 2, respectively. The bottom member 4 also has downturned flanges 8 and 9 along the sides. Thus a rigid frame is provided upon which all the parts of the switching unit are mounted.

The contact bank comprises ten parallel sections extending transversely of the switching unit and supported between the top and bottom plates 3 and 4. There is also a special section at one end of the unit, provided for a purpose

which will be described subsequently. The complete bank consists in part of elements individual to each section and in part of common elements, the latter comprising rigid flat conducting bars extending lengthwise of the switching unit through all the sections in series.

The contact bank may be explained more in detail in connection with Figs. 1 and 10. Considering the first regular bank section, there is

10 a rectangular strip of insulation 14 which extends transversely across the bottom plate 4, and on this strip 14 there is placed a similar strip 15. Resting on the latter strip is a strip of conducting material 16, which has a series of eleven contact springs, such as 17, 18, 19, and 20, Fig. 10, formed integrally therewith. The complete strip 16 with its integrally formed contact springs may be punched from a sheet of suitable material. Each of the insulating strips, 15 such as 14 and 15, may have an opening at each end, surrounded by a raised rim on the top of the strip, which is adapted to fit in an opening in a strip such as 16 and a corresponding depression in the bottom of the next insulating strip above. This is a customary expedient used to assist in aligning the bank elements.

Above the conducting strip 16 there is assembled an insulating strip 21, which is similar to 14 except that its upper surface is provided with a plurality of notches for receiving the contact element 22 and a series of ten conducting bars, such as 24, 25, and 26. The element 22 is provided with a terminal lug 23 which extends outside the bank assembly.

35 There are nine other bank sections to the right of the first section, which are identical with the first section. Fig. 1 shows the second section and part of the third, and also shows a special section at the left of the first regular section. In each of these sections the first fixed contact element at the edge of the bank is a contact element such as 22 which is individual to the section. In the special section and in the second section, Fig. 1, these contact elements are indicated at 51 and 52, respectively. The remaining fixed contact elements on this layer comprise the ten flat conducting bars, such as 24, 25, and 26, which extend through and are common to all the sections. These bars extend beyond the tenth section at the right hand end of the unit, and the projecting ends of the bars form terminals for the attachment of conductors.

55 The second layer of the bank is similar to the first, and in the case of the first regular section comprises the insulating strip 27, the conducting strip 28 having eleven integrally formed contact springs, such as 35, 36, 37, and 38, the notched insulating strip 29, the fixed contact element 30 provided with lug 31, and ten flat conducting

bars, such as 32, 33, and 34, the latter being common to all the sections, like bars 24, 25, and 26 of the first level.

The third layer of the bank is also similar to the first layer, and comprises in the case of the first regular section the insulating strip 39, the conducting strip 40 having eleven contact springs such as 48 formed integrally therewith, the notched insulating strip 41, the fixed contact element 42 having lug 43, and ten flat conducting bars, such as 44, 45, and 46. These bars are common to all the sections.

The conducting bars 44, 32, and 24 constitute a three-conductor line or trunk, bars 44 and 32 being the line bars while bar 24 is the test bar; that is, the two line conductors of a subscriber's line or of a trunk line may be connected to bars 44 and 32, while the test conductor is connected to bar 24. Thus it will be seen that the thirty bars in the first three layers of the bank represent ten three-conductor lines or trunks which are common to all sections of the bank. The three conducting strips 40, 28, and 16 of the first regular section are the three conductors of an intermediate trunk or link circuit which extends across or in coordinate relation to the ten lines or trunks represented by the ten sets of bars, such as 44, 32, 24, etc. Since the other nine regular sections of the bank are similar to the first section, there are in the first three layers of the bank ten of these intermediate link circuits each of which intersects each of the line or trunk circuits. Any link circuit can be connected to any line or trunk circuit by operation of the contact springs at the point of intersection. For example, the link circuit in the first regular section can be connected to the first line or trunk circuit by pressing contact springs 55, 36, and 18 into engagement, respectively, with bars 44, 32, and 24. The manner in which this is done will be explained later on.

There are twenty-seven additional layers in the bank above the first three layers which have been described, making thirty layers altogether. The additional layers may be considered as comprising nine sets of three layers each. In each set of three layers there are thirty bars corresponding to bars such as 44, 32, and 24, representing ten three-conductor lines or trunks. Also in each set of three layers there are thirty conducting strips, such as 40, 28, and 16, three to each of the regular bank sections, and constituting ten three-conductor link circuits. In the complete switching unit there are, therefore, three hundred of the flat conducting bars, such as 44, 32, and 24, representing one hundred three-conductor lines or trunks. There are also three hundred of the transverse conducting strips, such as 40, 28, and 16, arranged thirty to each regular bank section. Each such bank section, therefore, contains ten link circuits and, since there are ten regular bank sections, the total number of link circuits is one hundred.

The method by which the bank is built up may follow known practice in assembling such structures. It may be built up layer by layer on the bottom plate 4, as suggested in the previous description, and before the top plate 3 is assembled in the frame, suitable jigs being used for assisting in keeping the different sections in place as they are being assembled. When all the elements are in place the top plate 3 may be placed in position and pressure can be applied to compress the bank, after which the top plate 3 can be secured to the end members 1 and 2. To give addi-

tional security, rods such as 56, Fig. 1, may be provided, passing up through the bottom plate 4 and through the openings, such as 49 and 50, in the bank elements and threaded into the top plate 3. There may be one of these rods at each end of each bank section.

As previously mentioned, the line of trunk bars, such as 44, 32, and 24, extend to the right beyond the tenth regular bank section, and the ends of the bars are formed into terminal lugs for the attachment of wires or cable conductors. In Fig. 3 the ends of the top layer of bars can be seen, the end of top plate 3 being broken away. There are twenty-nine similar layers beneath the one shown.

As seen from the sectional view, Fig. 2, the three hundred line or trunk bars form ten vertical rows or groups of thirty bars each. The first group includes bars 24, 32, 44, and twenty-seven other bars in the same vertical row, the second group comprises bars 25, 33, 45, and twenty-seven other bars in the same vertical row, and so on. The numbering of the lines or trunks in each group may be from the top down. The first three bars in the first vertical row may be assigned to the first line or trunk, the next three to the second, and so on, bars 44, 32, and 24 being assigned to the tenth or 0 line or trunk of the group.

As previously mentioned, there are in each of the ten regular bank sections, ten intermediate link circuits, each comprising three conducting strips, such as 40, 28, and 16, which constitute the lowermost or tenth link circuit in the first regular section. This link circuit may be regarded as terminating in the three contact springs 48, 35, and 17, and each of the nine link circuits above terminates in a similar set of contact springs. Associated with the contact springs 48, 35, and 17 there is a set of fixed contacts comprising contacts 42, 30, and 22, provided with lugs 43, 31, and 23, and each of the other sets of contact springs has associated with it a similar set of fixed contacts. The several sets of fixed contacts in the first regular section are all connected in multiple by strapping at the terminal lugs; that is, lugs 43, 31, and 23 are connected, respectively, to the three corresponding lugs of the contact set immediately above, and the latter three lugs are connected, respectively, to the next three lugs above, and so on. The ten contact sets of the first section thus strapped together constitute the multiple terminals of a trunk line, to which any link circuit of the first section may be connected by pressing its terminal contact springs, such as 48, 35, and 17, into engagement with their associated fixed contacts, such as 42, 30, and 22.

Each of the nine other regular bank sections 60 is wired just as described in the case of the first regular section, and there are, therefore, ten trunk lines which terminate in multiply connected contact sets in the ten regular bank sections, respectively. These trunk lines may be 65 outgoing trunks or incoming trunks, depending on the switching stage at which the unit is used, as will be explained in detail later on.

The special bank section which is shown to the left of the first regular section in Fig. 1 may 70 be the same as the regular sections insofar as the contact elements contained therein are concerned. However, the function of this special bank does not involve the closing of any circuits to the line conductors, and hence the conducting strips which correspond to strips, such as 40 and

28, may be omitted, as indicated in the drawings. Plain metal strips having no contact springs and functioning as spacers may be inserted instead. The first, fourth, seventh, etc. layers are equipped with conducting strips such as 57, having contact springs, such as 53 and 54. At each of these strips the first contact spring such as 53 is bent up and soldered to the individual contact element such as 51 above. The ten lugs, such as 58 and 59, therefore, can be used as terminals for the ten conducting strips such as 57. The conducting strip 57 terminating at lug 58 and having ten contact springs such as 54 constitutes means for extending a connection to the test conductor of any one of the ten lines or trunks of the bottom layer in the bank, and the other similar conducting strips above have the same functions with respect to the lines or trunks in the corresponding layers of the bank.

The mechanism for operating the contact springs to the bank will now be explained, with reference particularly to Fig. 2, which shows a section taken just to the right of the first regular bank section as seen in Fig. 1. Considering the first vertical row of bars, such as 44, 32, and 24, with their associated contact springs, such as 55, 36, and 18, the latter are operated by means of a vertical longitudinally movable operating bar having a plurality of projections thereon equal to the number of contact springs in the vertical row, or thirty altogether. This operating bar comprises a rod 60 on which there is molded a cylindrical body 61 of insulating material having projections, such as 62, 63, and 64. There are ten of these operating bars assigned to the first bank section, as seen in Fig. 2.

The ten operating bars above referred to are provided with bearings which are supported on the top and bottom plates 3 and 4. The top plate is slotted at 67, Fig. 4, and the bottom plate at 68, Fig. 5, to permit the operating bars to be inserted after the bank has been assembled. The bars are, of course, inserted in such a manner that the projections 62, 63, etc. are not interfered with by the bars 44, 32, etc., and are then rotated 90° to the positions in which they are shown. The upper bearing is formed by a notched strip 69 and a strip 70 having a single long recess in one side thereof, these strips being assembled from opposite sides of the row of bars 60 and being secured to the frame plate 3 by means of two screws. As can be seen from Fig. 6, the bars 60 lie in the notches 71 of strip 69 where they are retained by the strip 70. At its lower end each rod 60 has a rectangular bend formed therein, providing a short section such as 66 extending parallel to the main section of the rod, as shown in Fig. 5. The lower bearing is formed of a strip 72, having notches for each rod 60 and its parallel section 66, and a retaining strip 73. These strips are secured to the lower frame plate 4 by means of screws. It will be clear that the described arrangement prevents rotation of the rods 60.

The contact springs, such as 18, 36, and 55 are tensioned lightly against the projections, such as 62, 63, and 64. The projections 63, 64, etc. rest on the bars 24, 32, etc., which support the weight of the bar 60—61. Each bar is slidable vertically to close simultaneously all the contacts in the associated vertical row. When bar 60 is raised vertically, for instance, all of the thirty contact springs, such as 18 and 36, are pressed into engagement with the corresponding bars 24, 32, etc.

5 Each of the ten regular bank sections is, of course, provided with a set of ten vertical operating bars similar to those described in the case of the first section. There are, therefore, one hundred of these operating bars.

10 The mechanism for raising the operating bars will next be described. To accomplish this purpose there is provided at each regular bank section a so-called gate and a magnet for operating it. The gate and associated magnet at the first regular bank section is typical of the others and will be described briefly.

15 The magnet is indicated at 75 and includes core 76 and pole pieces 77 and 78 secured to opposite ends of the core. The magnet structure is mounted on the bottom plate 4 of the frame by means of brackets 82 and 79 secured to pole pieces 77 and 78 by screws 85 and 88, respectively, and to flanges 8 and 8 by screws 83 and 84, respectively. The magnet has an armature 100, pivoted on brackets 82 and 79 by means of pivot screws 87 and 88, respectively. Armature 100 has two arms 101 and 102, which extend to the right a short distance beyond the pole pieces 77 and 78, as seen in Fig. 1.

20 The gate comprises two vertical pieces of angle material 91 and 92, which are pivoted on the upturned ends of arms 101 and 102, respectively, by means of pivot screws 89 and 90, said pieces 91 and 92 being held together at the top by a cross member 94. The gate has bearings at the top comprising notches in the ends of strip 69, as shown in Figs. 2 and 6. When magnet 75 is energized, armature 100 is attracted and raises the gate, the vertical side pieces 91 and 92 sliding in the notches in strip 69. When the magnet is released, the gate restores by gravity and comes to rest with projections 106 and 107 engaging flanges 6 and 7 of the top frame plate 3.

25 40 The magnet 75 has associated therewith a set of contact springs indicated at 103. The bracket 79 includes a part 80 extending at right angles to part 79 and having a downwardly-extending continuation 81 on which the springs 103 are mounted by means of the usual insulators and screws. The springs are actuated by means of a stud 105 of insulating material carried on the arm 104 of armature 100.

30 45 50 Mounted on the cross member 94 at the top of the gate there is a comb-shaped member 96 provided with the spring fingers such as 97. These fingers are all lightly tensioned to the right against the cross bar 95 which extends across the gate a short distance below cross member 94. Each spring finger 97 is notched at one side, whereby there is formed at the end a lifting arm 98 the upper edge of which is located just to the right of and slightly below the hook 65 on rod 60. The relation between the lifting arms 98 and hooks 65 can be seen clearly from Figs. 1 and 2. These spring fingers and the lifting arms at the ends thereof are provided for raising the vertical operating bars 60.

55 60 65 As mentioned previously, there is a gate for each regular bank section, or ten gates altogether. From a circuit standpoint the ten gates correspond to the ten trunks, incoming or outgoing, which terminate in the ten bank sections, respectively.

70 75 75 The spring fingers 97 of each gate are all normally ineffective to raise their associated operating bars when the gate is lifted. They are rendered effective selectively by means of a set of ten so-called "tens bars" which will now be described with reference to Figs. 1, 2, and 3.

One of the tens bars is indicated by the reference numeral 111. This bar and nine other similar bars extend lengthwise of the unit in spaced relation just above the upper frame plate 3. The bars are slidably supported at the left in notches in the transverse bar or strip 112 and are retained therein by means of a strip 113. At the right hand end the bars are slidably supported in a notched bar which is similar to bar 112 and are retained in position by a strip 114. All of the 10 ten bars can be seen in Fig. 3, and also in Fig. 2, from which it will be clear that the bars are equal in number to and are spaced with definite relation to the spring fingers such as 97 on the gates.

The bar 111 is forced to the right, as seen in Fig. 1, by means of spring 115 and has an offset portion 110 at the end which limits its movement in this direction by engagement with the edge of strip 113. The spring 115 is compressed between 20 the angle strip 116 at one end and the bar 110 at the other and being slightly longer than the distance between these parts it has a curved formation, as seen in Fig. 1. Each of the other nine bars such as bar 111 is provided with a spring such as spring 115, as can be seen clearly from Fig. 3.

The bar 111 is provided with an upwardly-extending projection or cam 121 which is located just to the right of the lower end of spring finger 97, as seen in Fig. 1, and with nine similar projections or cams, such as 122 and 120, which are located just to the right of the spring fingers corresponding to finger 97 on the nine other gates, respectively. These ten projections on bar 111 are adapted to bend the ten spring fingers such as 97 to the left and beneath the associated hooks such as 65 when the bar 111 is moved longitudinally to the left. Each of the other nine tens bars is similarly provided with ten upwardly-extending projections which are adapted to operate the ten spring fingers in the corresponding row.

The tens bars described in the foregoing are selectively actuated by means of ten magnets, such as 131, 132, and 130, which are mounted on the top frame plate 3 in a manner similar to the way in which magnets 75 are mounted on the lower frame plate 4.

Magnet 131, which is the same as the others, includes the usual core 142 and pole pieces 137 and 138, which are secured to brackets 133 and 136 by means of screws 143 and 144, respectively. The two brackets, in turn, are secured to the flanges 6 and 7 of top plate 3 by means of screws 145 and 146, respectively. The magnet 131 has an armature 231, which is pivoted on brackets 133 and 136 by means of pivot screws 147 and 148, respectively. The armature 231 has an upwardly-extending arm 140, for operating a set of contact springs which has been omitted in order to avoid obscuring the parts beneath it, and a downwardly-extending part 139 which merges into a transverse member 251, Fig. 1, formed integrally therewith and spanning all the tens bars such as 111.

When the magnet 131 is energized the armature 231 is attracted and the member 251 is moved to the left, coming into engagement with a vertical member 241 riveted to the tens bar 111 and moving bar 111 to the left. Only bar 111 has a vertical member such as 241 associated with member 251 and consequently only the tens bar 111 is actuated by the energization of magnet 131. The next tens bar has a vertical member 242 which is associated with the transverse 70

member 252 actuated by the armature 232 of magnet 132, and each succeeding tens bar has a similar vertical member, which is, however, in each case disposed one position to the right of the corresponding vertical member on the preceding tens bar. Thus the armature of the tenth or last magnet 130, seen in Fig. 3, has a transverse member which cooperates with the vertical member 240 on the tenth or last tens bar. From the foregoing it will be understood that the ten vertical members, such as 241, 242, and 240, are positioned on a diagonal line, viewing the unit from the top, which extends from the first member 241 on the first tens bar to the last member 240 on the tenth tens bar. Each armature such as 231 is provided with a transverse member such as 251 spanning all the tens bars merely for the sake of uniformity, that is, to enable all the armatures to be made alike.

The bracket 133 includes a portion 233 which extends parallel to magnet 131 for a short distance and which has a vertical extension 234 on which a set of contact springs are mounted in conventional manner. These springs are shown in the case of magnet 132, and are indicated by reference character 236. They are operated by the insulating stud 141 on arm 140 of armature 232. Each tens magnet is provided with a similar set of contact springs.

The operation of any tens bar results in the operation of mechanism shown in Figs. 1 and 3 for closing all the contacts in the corresponding vertical row in the special bank section hereinbefore described. The contacts in the row corresponding to tens bar 111 and including contact spring 54 are operated by means of a vertical operating bar comprising a rod 118 and a cylindrical body 119 molded thereon with projections extending underneath the contact springs such as 54. This operating bar may be similar to bar 60-61, Fig. 2, although only one-third of the side projections are used. The bar 118-119 is supported in bearings the same as bar 60-61 and the other bars in the same transverse row. The upper end of rod 118 is bent at right angles to the main portion of the rod and the short horizontal section thus formed carries a roller 117 which rests on the spring 115. When the tens bar 111 is actuated, that is, moved to the left, the spring 115 assumes a greater curvature and the roller 117 is raised, carrying with it the operating bar 118-119. Thus all the contact springs such as 54 in the vertical row are operated.

There are nine other operating bars similar to bar 118-119, all located in the same transverse row. The rollers such as 117 for operating these bars can be seen in Fig. 3.

It will be recalled now that each of the regular bank sections includes ten intermediate link circuits extending transversely of the unit. The lower link circuit of the first section comprises the conducting strips 40, 28, and 16, and terminates in the contact springs 48, 35, and 11, these three springs constituting a set. There are nine similar sets in a vertical row above the set of springs 48, 35, and 11. The means for selectively operating these sets of contact springs will now be described.

There are ten operating members for the ten sets of contacts above referred to, each member comprising a recessed block of insulating material having projections thereon for operating the associated contact springs. Fig. 2 shows the first

and second blocks 160 and 161, and the last block 162. Block 160 will be described in detail. It may be molded in one piece of some plastic compound and has three projections 166, 167, and 168 which extend beneath the three contact springs 172, 173, and 174, respectively, of the associated set. These projections rest, respectively, on the three contact members, such as 176 and 177, which are immediately beneath them. On the side opposite the projections 166-168, the block 160 is recessed as indicated at 170, Figs. 2 and 8. There is also a longitudinal slot 169, having the same depth as recess 170. The slot 169 is of the proper width to receive the lateral extension 93 of the side angle member 91 of the gate. As shown in Fig. 2, this member is wider where it passes the bank, the inwardly-extending portion being indicated at 93. The block 160 is thus loosely supported by the gate in the position shown in Fig. 2, with its weight resting on the contact members such as 176. The other blocks, such as 161 and 162, are supported the same way. It will be understood that when the gate is raised the part 93 thereof slides in the slots 169 of the several blocks and these blocks remain stationary. Means is provided, however, for moving a selected one of the blocks along with the gate when it is raised. The selecting means includes a set of ten so-called "units bars" which will now be described.

Seven of the ten units bars are shown in Fig. 1. The first two bars are indicated at 181 and 182, and the last or tenth bar at 180. For the purpose of supporting these bars there are provided two vertical strips 187 and 189 which in turn are supported on angle pieces 186 and 188, the latter being secured to the flanges 7 and 9 on the top and bottom plates of the frame. The angle piece 186 not only supports the strip 187, but also supports the units magnets, as will be explained presently. The strips 187 and 189 are slotted on the side toward the unit and the slots are deep enough to extend some distance beyond the edges of angle pieces 186 and 188, thus forming rectangular slots for receiving the bars, such as 181, 182, and 180, as shown in Fig. 2. The bars fit loosely and are movable longitudinally to the left, as seen in Figs. 1 and 3. Each bar has a series of ten projections, such as 183, 184, and 185, which cooperate with spring fingers on the gates for operating the blocks such as 160.

The particular block 160 is actuated by means of a spring finger 163, shown in Figs. 2 and 8. At its upper end the spring finger 163 is attached to the angle piece 91 of the gate for the first section. From its point of attachment to the gate the main body of the finger extends angularly downward until a point outside the block 160 is reached after which it extends vertically downward and terminates in an angularly disposed lifting arm 164, which extends to the right, as seen in Fig. 2. Just above the lifting arm 164 and in alignment with the projection 183 on bar 181 there is a projection or arm 165, which extends through opening 190, Fig. 1, in the gate. The parts 164 and 165 are formed integrally with the spring finger 163, which may be punched from a sheet of suitable material and bent to the shape shown.

When the units bar 181 is moved longitudinally to the left, the projections 183, 184, etc., engage the projections 165, 165', etc. on the upper spring fingers of all the gates and move them into operative relation to the associated blocks such as 160. The projection 183, for example, engages

projection 165 and bends spring finger 163 far enough so that the lifting arm 164 enters the recess 170 of the block. Now if the gate 91-92 is raised, the angularly disposed lifting arm 164 will engage the surface 171 defining the upper side of the recess and will raise the block along with the gate, thereby pressing the contact springs 172, 173, and 174 into engagement with their associated contact members such as 175. The other blocks, such as 161 and 162, remain unoperated.

The tens units bars such as 181 are selectively operated by means of a set of ten magnets which are mounted at the left hand end of the unit on the vertical angle piece 186. The magnet 211, associated with the first tens bar 181, comprises the usual core and a heel piece 201, the latter being secured to the angle piece by means of screws 209 and 210. The armature 202 has a knife edge pivot on the end of the heel piece 201, and is provided with an extension 203 the end of which engages a notch in the end of bar 181. It will be seen that when magnet 211 is energized, the armature 202 will be attracted and bar 181 will be moved longitudinally to the left by means of the armature extension 203.

Magnet 211 also operates a set of contact springs by means of the insulating pin 204 secured to the armature 202. These contact springs are mounted on a bracket which forms part of heel piece 201 and comprises a part 205 bent at right angles to the main body of the heel piece and a part 206 which is bent at right angles to part 205 and which is parallel to the heel piece. The springs are secured to the part 206 by means of the usual insulators and screws. A spring 207 is inserted next to 206 and serves to retain the armature 202 in position.

As shown clearly in Fig. 1, each of the outer units bars such as 182 has associated with it an operating magnet such as 212 which is similar to magnet 211.

It should be stated that the sets of contact springs which are shown associated with the gate magnets, tens magnets, and units magnets are to be considered merely as indicating that each of these magnets may have and operate a set of contact springs in addition to performing its other function. The exact spring combination used in any case will depend on the switching stage at which the unit is used and may vary even at each stage. The spring combinations used in a representative system are described in connection with the circuit drawings.

The mechanical details of establishing a connection by means of the described switching unit can perhaps be best understood by reference to Fig. 9, which shows in perspective a part of the first regular bank section and part of the associated gate 91. It may be assumed that there are one hundred lines terminated in the switching unit, the line numbered 11 being terminated in the bars 195, 196, and 197. There may also be ten trunks terminated in the unit, the first trunk being connected to contact members 175, 176, and 177, which are multiplied to the other similar sets of contact members in the same vertical row, as previously described. In order to connect line 11 to the first trunk line, the tens bar 181 and the units bar 181 are actuated, followed by lifting the gate 91.

When tens bar 181 is moved to the left, its projection 165 engages the end of spring finger 97 and bends the spring far enough so that lifting arm 98 passes beneath the hook 65 on vertical operating bar 60-61. When units bar 181 is

moved to the left, the projection 183 thereon engages arm 165 on spring finger 163 and bends the latter far enough so that lifting arm 164 passes underneath the edge 171 of the recess in block 160. Now when the gate 91 starts to rise, lifting arm 98 engages the hook 65 and slides along the hook a short distance until the arm engages the vertical portion of rod 60. The slight additional bending of spring finger 97 which is involved in this operation moves arm 98 away from projection 121. At the same time the angularly disposed lifting arm 164 engages the inclined surface 171 on block 160 and slides along said surface until the lower end of spring finger 163 engages the angle piece 91 of the gate, thus moving arm 165 away from projection 183. Further movement of the gate now results in the raising of operating bar 60-61 by the lifting arm 98 and the raising of block 160 by the lifting arm 164.

The operating bar 60-61, when raised as described in the foregoing, connects the ten lines terminating in the first vertical row of line bars to the ten intermediate link circuits in the first bank section, and more in particular it connects the line 11 to the uppermost or first link circuit by pressing contact springs 192, 193, and 194 into engagement with bars 195, 196, and 197, respectively. The first link circuit terminates in contact springs 172, 173, and 174, which are pressed into engagement with contact members 175, 176, and 177, respectively, by the block 160. Thus the line and trunk are connected.

The connection is maintained by the gate 91, which remains in operated position. The tens bar 111 and the units bar 181 are released as soon as the gate has operated. The spring finger 97 is retained in operative relation to bar 60-61 by the hook 65, and likewise the spring finger 163 is retained by the inclined surface 171 on block 160. When the gate is restored, the operating bar 60-61 and the block 160 are positively restored by the tension in the operated contact springs, such as 192 and 172. On complete restoration of the gate, the lifting arms 98 and 164 drop below hook 65 and surface 171, respectively, and the spring fingers 97 and 163 are permitted to restore.

As many as ten connections may be in existence simultaneously; that is, all ten of the trunks associated with the ten bank sections may be in use at the same time. The establishment of all these connections is controlled by the tens and units bars, which are common to the ten gates. Further details of the way in which connections are established, dealing more particularly with the circuits involved, will be explained in connection with the description of the complete telephone system and its operation.

The circuit drawings, Figs. 11 to 14, inclusive, show a one thousand-line automatic telephone system using switching units of the type described herein, which function as finders, selectors, and connectors. The system may comprise ten groups of subscribers' lines, each comprising one hundred lines, and each served by a switching unit operating in the finder capacity to connect calling lines to idle trunks. The finder stage therefore requires ten switching units. The trunks from the finder stage extend to a group of ten switching units operating as selectors, and from this stage other trunk lines extend to ten more switching units, one for each group of subscribers' lines, which function as connectors. There may be altogether thirty switching units,

or ten at each of the three switching stages. The trunking between the different switching stages may conform generally to known practice.

The circuit drawings show diagrammatically the apparatus and circuits involved in the establishment of a connection between a calling station A, Fig. 11, which is connected to a line in the second group of the system, and a called station B, Fig. 13, which is connected to a line in the same group, together with sufficient additional apparatus and circuits so that the manner in which other connections are established may be readily understood. The telephone number at station A is 221 and that of station B is 212.

The line conductors 300 and 301 of the line of station A extend to the central office where they terminate in the individual line equipment comprising the line relay 306 and the cutoff relay 307. From the line equipment the conductors 300, 301, and the test conductor 302 extend to the bars 316, 317, and 318 of the finder switching unit assigned to the second group of lines, and three so-called normal conductors 303, 304, and 305 extend to the corresponding connector switching unit. The line and cutoff relays associated with lines having telephone numbers 222, 211, and 212 are also shown.

The first sub-group of subscribers' lines, comprising lines numbered from 211 to 210, terminates in the first vertical group of line bars in the finder switching unit, counting from the left in Fig. 2, which may conveniently be referred to in order to explain how the lines are connected. Line No. 211 terminates in the first set of line bars at the top of this vertical row, while line No. 210 terminates in the bottom set of line bars, corresponding to bars 44, 32, and 24.

The second sub-group of subscribers' lines, comprising lines numbered from 221 to 210, terminates in the second vertical row in the same manner, the third sub-group of lines, numbered from 231 to 230, terminates in the third vertical row, and so on. The line bars 316, 317, and 318 to which the line of station A, Fig. 11, is connected are therefore the first three bars counting from the top in the second vertical row, as the finder switching unit is seen in Fig. 2.

Fig. 11 shows portions of the first and second regular bank sections and a portion of the special bank section. The vertical operating bar 321, shown diagrammatically, corresponds to operating bar 60, Fig. 2, and bar 323 to the corresponding bar in the second bank section. Operating bars 322 and 324 are the second operating bars in the same transverse rows that include bars 321 and 323, respectively. That is, bars 321 and 323 are associated with the first sub-group of lines and bars 322 and 324 with the second sub-group of lines. Only three sets of line bars in each of two sub-groups are shown. Bars 319 and 320 are the first and second operating bars of the special section.

Fig. 11 also shows three blocks 325, 326, and 327 in the first bank section, which correspond to the first three blocks such as 160 in Fig. 2. The first three blocks in the second bank section are also shown. The three contact springs shown associated with each of these blocks constitute terminals of an intermediate link circuit, as previously explained. The three contact springs 344, 345, and 346, associated with block 325, are terminals of the first link circuit in the first section and are multiplied to the first set of contact springs 350, 351, and 352 in the first vertical

row of the first section, to the first set of contact springs 353, 354, and 355 in the second row, and so on. The multiple is shown as being composed of conductors 347, 348, and 349, but in reality the springs, such as 344, 350, 353, etc., are all formed from one continuous conducting strip, as previously described. The other link circuits are similar. In the special bank section contact springs 356, 357, etc., are formed of one continuous strip, whereby they are multiplied together. Conductor 358 in actual practice is connected to a lug such as 58', Fig. 1. This lug is part of a contact member 51', to which the first contact spring 53' is soldered. Conductor 358 therefore connects to the conducting strip having contact springs 356, 357, etc., represented in Fig. 11 by conductor 361, by way of a lug such as 58', contact member 51', and contact spring 53'. The other conductors, such as 359 and 360, are connected the same way.

The conductors 365, 366, and 367 constitute an outgoing trunk which extends from the first regular bank section to a selector unit. At the first regular bank section the trunk is connected in multiple to sets of contact members, such as 362, 363 and 364, which correspond to contact members 175, 176, and 177, Fig. 2. The conductors are actually terminated at lugs projecting from the sides of the contact members, as indicated in Figs. 1 and 10. There are ten outgoing trunk lines, of which the second trunk 368 is also shown in Fig. 11.

The drawing, Fig. 11, also shows the first and second tens magnets 331 and 332, the first three units magnets 341, 342, and 343, and the first two gate operating magnets 371 and 372. The relays 381 and 382 are two of ten guard relays associated with the ten outgoing trunks, respectively. Relay 337 is a control relay the function of which will be described.

The trunk line comprising conductors 365, 366, and 367 extends to a selector unit which is partly shown in Fig. 12, where it appears as an incoming trunk at the second regular bank section. This selector unit is similar to the finder unit and consequently need not be described in detail. It will be desirable, however, to explain briefly the trunking connections and certain other features.

There may be ten incoming trunks, terminating at the ten regular bank sections, respectively. Two of these trunks are shown, trunk 380 which terminates in the first section and trunk 365—367 which terminates in the second section, as previously stated.

The bars which extend lengthwise of the unit and which in the finder unit correspond to subscribers' lines correspond to outgoing trunk lines in the selector unit. Thus the first vertical row of bars (ten sets of three bars each) are terminals of a group of ten outgoing trunks which extend to the first connector unit. The first set of bars in this group comprises bars 450, 451, and 452. The second vertical row of bars are terminals of a group of ten outgoing trunks which extend to the second connector unit. The first set of bars in this group comprises bars 453, 454, and 455. The other eight vertical rows (not shown) terminate outgoing trunks extending to the other eight connector units, respectively.

The drawing shows the operating bars 481, 483, 482, and 484, which are associated with the first two vertical rows of the first two bank sections, and also shows operating bars 485 and 486 in the special bank section. The first two tens magnets 75

are shown at 431 and 432, and the first three units magnets at 441, 442, and 443. Magnets 471 and 472 are the gate operating magnets for the first two bank sections.

5 The selector units handles calls partly on a numerical basis; that is, groups of outgoing trunks are selected in accordance with the initial digits in subscribers' numbers, and therefore is provided with control units each of which includes digit registering means. One of these control units is shown at the left of Fig. 12 and comprises relays 400 to 411, inclusive, and relay 470. From the control unit ten marking conductors extend to the ten tens magnets, respectively, of the selector unit, these conductors being multiplied to the other control units for the same selector unit. Two of the marking conductors are shown and are connected to tens magnets 431 and 432.

20 There may be two or three control units provided for each switching unit, or more if necessary, but in any case the number of such control units will be considerably smaller than the number of incoming trunks, and each control unit therefore will serve a plurality of trunks. All the incoming trunks which are served by the same control unit are normally connected in multiple to such unit, as shown in the case of trunks 380 and 365—367, both of which normally extend to the control unit shown through contacts of their associated gate operating magnets 471 and 472. In order to give the subscribers the maximum access to the control units, each control unit is assigned trunks coming from different finder units. In other words, the outgoing trunks at each finder unit preferably all utilize different control units at the selector end and to attain this result may be routed in part to different selector units according to known trunking practice.

40 Relays 411 and 412 are sequence control relays. There is one of these relays for each control unit.

The drawing, Fig. 12, also shows a timer comprising cams 493 and 494, which may be mounted on a shaft rotating continuously at a slow constant speed. This timer is common to all selector and connector units and may be of any well known type.

50 Fig. 12 shows one outgoing trunk at the right, which is the first trunk in the second group, and comprises conductors 460, 461, and 462. This trunk extends to the connector unit, Fig. 13, serving the second group of subscribers' lines, 55 where it is associated with the first regular bank section. The nine other trunk lines of the group extend to the same connector unit and terminate in the second to tenth bank sections. The connector unit is accessible from all the selector units and therefore the ten trunk lines of the group are multiplied in known manner to the other selector units. The same is true of the other groups of trunks outgoing from the selector units.

60 65 The connector switching unit partly shown in Fig. 13 is similar to the finder and selector units and consequently need not be described in detail. The drawing shows two of the ten tens magnets, at 531 and 532, and three of the tens units magnets, at 541, 542, and 543. The gate operating magnets for the first and second bank sections are shown at 571 and 572.

70 The one hundred subscribers' lines of the second group are connected to the line bars of the connector unit in the same way that they are

connected to the line bars of the finder unit, Fig. 11. Thus the line of station B, the telephone number of which is 212, is connected to the second set of line bars in the first group, these bars being indicated at 544, 545, and 546.

The ten incoming trunks may be regarded as terminating in the ten regular bank sections, respectively, as previously stated, but since the trunks do not extend directly to their respective bank sections, the arrangement may properly be explained briefly. Trunk 460-462, for example, normally extends by way of contacts of gate operating magnet 571 and trunk 510-512 to the control unit which is shown in Fig. 14. When magnet 571 is energized, however, trunk 460-462 extends to trunk 515-517 (the latter terminating in the first bank section) by way of the battery feed unit comprising relays 520 to 523, inclusive. Each of the other incoming trunks is arranged the same way. Thus trunk 555, the only other trunk shown, normally extends to the control unit in Fig. 14, but upon the energization of gate operating magnet 572 it is extended to the second bank section by way of the battery feed unit 554.

There are a number of control units provided for the incoming trunks to the connector group, one of these units being shown in Fig. 14, as previously mentioned. The control unit shown comprises relays 600 to 621, inclusive, also relay 570, and includes means for registering two digits in a called subscriber's number. A group of ten marking conductors extends to the tens magnets of the connector switching unit and a similar group of ten marking conductors extends to the units magnets of the switching unit. Conductors 671 and 672 are two of the tens marking conductors, while conductors 661, 662, and 663 are three of the units marking conductors. Two additional conductors 673 and 674 extend to the switching unit as shown. All these conductors except conductor 674 are multiplied to other control units associated with the same connector unit.

Relays 621 and 622 are sequence relays, there being one of these relays provided for each of the control units.

The telephone system or exchange also includes the usual power equipment, such as ringing machine, busy signalling machine, and a source of current such as a storage battery with its charging equipment. This apparatus is well known and is not shown in the drawings. It is assumed that the positive pole of the storage battery is grounded. All circuit conductors shown as connected to ground are connected in practice to the positive pole of the storage battery, while all circuit conductors shown terminating in an arrow labeled negative (-) are in practice connected to the negative or ungrounded terminal of the storage battery.

The operation of the equipment in establishing a connection between the line of station A, Fig. 11, and the line of station B, Fig. 13, will now be explained. When the receiver is removed at station A, a circuit is completed over the line comprising conductors 300 and 301 for the line relay 306, the said circuit extending from ground by way of the left hand contact 308' of the cutoff relay 307, line conductor 301, talking instrumentalities at station A, line conductor 300, right hand contact 312 of the cutoff relay, and left hand winding of the line relay 306 to battery. Upon energizing, the line relay connects the test conductor 302 to its own right hand

winding and to the private normal conductor 305, thereby placing negative battery potential on the test conductor. At the same time, the line relay closes a circuit at contact 308 for the tens magnet 332, said circuit extending from ground by way of contact 308, the normally closed contact 309, conductor 313, and winding of the tens magnet 332 to conductor 335, whence the circuit continues through serially related chain contacts on all of the tens magnets to negative battery at contact 338 of relay 337. The continuity of the above circuit of course depends on no tens magnet being energized. Assuming that no tens magnet is energized when the line relay 306 pulls up, the closure of contact 308 completes the circuit for tens magnet 332 as described and the magnet energizes, locking it self at contact 333 and at the same time breaking the series chain circuit to prevent any other tens magnet from energizing.

The operation of the tens magnet 332 operates the second tens bar, thus preparing for the operation of the operating bars 322, 324, etc. The movement of the tens bar also raises the operating bar 320 in the special bank section, thus connecting the test conductors of all of the lines in the second sub-group to the units magnets. The test conductor 302 has been connected to battery by energization of line relay 306 as previously described, and accordingly a circuit is now closed for the units magnet 341 over a path which extends from ground by way of contact 339 of relay 337, serially related chain contacts on all of the units magnets, left hand winding of magnet 341, rectifier 385, conductor 358, contact spring 357, bar 318, conductor 302, contact 310 of line relay 306, right hand winding of line relay and left hand winding of cutoff relay 307 to battery. The left hand winding of the units magnet 341 is of comparatively high resistance and accordingly the cutoff relay 307 is not energized over the above circuit. The units magnet 341 energizes, however, and closes a locking circuit through its right hand winding, at the same time breaking the chain circuit over which it was originally energized. This chain circuit, it will be understood, prevents more than one of the units magnets from energizing in the event that two subscribers' lines in the sub-group should be calling at the same time. The energization of the units magnet 341 of course operates the associated units bar, which prepares for operation of the blocks 325, 328, etc. by their associated gates.

When the units magnet 341 is energized, a circuit is closed for the guard relays, such as 381, 382, etc., of all the outgoing trunk lines which are idle at the time. In the case of guard relay 381 the circuit extends from ground at contact 383, by way of serially related chain contacts on the ten guard relays, such as 381, 382, etc., lower winding of guard relay 381, rectifier 379, test conductor 367 of the first outgoing trunk line, normally closed contacts of the gate operating magnet 472, Fig. 12, contact 495 of relay 470, conductor 499, and normally closed contact 415 of the release relay 401 in the control unit to battery. If the second trunk line is idle, a similar parallel circuit extends through the lower winding of the guard relay 382 and over the test conductor of the second outgoing trunk to battery at the control unit in which this trunk line terminates. The same is true of the other guard relays; that is, the lower windings of all these guard relays are energized in parallel over their

associated test conductors provided the trunk lines are idle, the idle condition being indicated by the connection of the test conductors to battery at the control units in which they normally terminate. It will be assumed that the first outgoing trunk line is idle and accordingly the first guard relay 381 is energized over the circuit traced. A plurality of other guard relays may start to energize at the same time, but since relay 381 is the first in the chain, it locks itself at its contact 373 and opens the chain circuit, thus preventing any of the other guard relays from fully energizing. On energizing, relay 381 prepares a circuit for relay 337 at contact 376 and at contact 378 closes a circuit for the first gate operating magnet 371.

When the magnet 371 energizes, it raises the gate associated with the first bank section and thereby also raises the operating bar 322, thus connecting the ten lines of the second sub-group of subscribers' lines to the ten intermediate link circuits of the first bank section. At the same time the gate raises the block 325, thereby connecting the first or uppermost link circuit to the outgoing trunk line associated with the first bank section, that is, to the first outgoing trunk line. By these operations the conductors 300 and 301 of the calling line are extended by way of line bars 316 and 317, contact springs 353 and 354, contact springs 344 and 345, contacts 362 and 363, trunk conductors 365 and 366, and contacts 475 and 476 of the gate magnet 472, Fig. 12, to the winding of the line relay 400 of the control unit shown in Fig. 12. The line relay 400 is accordingly energized and at contact 413 closes a circuit for the slow-acting release relay 401. The latter relay, on energizing, disconnects the test conductor 499 from battery at contact 415 and connects it to ground. The placing of ground on the test conductor completes a holding circuit which extends back from the control unit by way of conductor 499, contact 495 of relay 470, contacts of gate magnet 472, test conductor 367, contact 364, contact spring 346 of the link circuit, contact spring 355 of the link circuit, bar 318, conductor 302, contact 310, right hand winding of the line relay 306 and left hand winding of the cutoff relay 307 to battery. A branch of this holding circuit extends through resistance 378 and locking contact 374 of the gate operating magnet 371 to battery. The cutoff relay 307 energizes over the above described holding circuit and at its armature 308 disconnects ground from the line conductor 301. At armature 312 the cutoff relay disconnects battery from line conductor 306 and at armature 309 it removes ground from conductor 318.

When the gate operating magnet 371 pulls up as previously described, it closes a circuit for relay 337 at contact 371. On energizing, relay 337 opens the circuit of the energized tens magnet 382, thereby permitting this magnet to de-energize. The operated tens bar is accordingly restored to normal, and likewise the operating bar 320 in the special bank section. Relay 337 also opens the circuit of units magnet 341, which deenergizes and restores the operated units bar. On deenergizing, the units magnet 341 also breaks the circuit of the guard relay 381 which falls back and opens the initial energizing circuit for the gate operating magnet 371. This magnet remains energized, however, over the previously described branch holding circuit, including resistance 378. The latter resistance is rather high and permits only sufficient current to flow to

5 maintain magnet 371 in operated position. The guard relay 381 also breaks the circuit of relay 337, which accordingly falls back and again places battery on the chain circuit associated with the tens magnets and ground on the chain circuit associated with the units magnets. These magnets are accordingly placed in normal condition ready for response to another calling line.

10 Before continuing with the operation, the purpose of the rectifiers which are included in the initial energizing circuits of the units magnets and the guard relays may be briefly explained. These rectifiers are provided in order to prevent false operation by so-called "sneak currents." In the case of the units magnets, for example, if the first line of the second sub-group is busy, there will be a ground on the test conductor 302, as explained in the foregoing. Now, if the second line in the sub-group makes a call, when the 15 tens magnet is energized, the operating bar 320 is raised to connect up all the test conductors of the ten lines in the sub-group, thus establishing a circuit including the test conductor of the calling line, magnets 342 and 341 in series, and the grounded test conductor of the first line. Since the units magnet 341 is the first in the chain, it would energize and lock and prevent the units magnet 342 associated with the calling line from energizing. This result is prevented by the rectifier 379 which prevents any flow of current to the grounded test conductor 302 through magnets 342 and 341 in series. In other words, the presence of these rectifiers in the circuits of the units magnets insures that each of these magnets can only energize by current flow to ground by way of the chain circuit and contact 339 of relay 337. The situation is somewhat similar in the case of the guard relays. It will be noted, for example, that at any time when the first outgoing trunk line is busy and the second outgoing trunk is idle, there will be a circuit extending from battery on the test conductor of the second outgoing trunk line by way of guard relays 382 and 381 in series to the grounded test conductor 367 of the first trunk line. No current can flow in this circuit, however, because of the presence of rectifier 379. These rectifiers associated with the guard relays therefore insure that each guard relay can energize only over a 20 circuit to ground through the chain contacts and the contact on an energized units magnet. In the foregoing explanation it has been necessary to take into consideration the actual direction of current flow, which is from the negative or ungrounded pole of the battery to the positive or grounded pole. This is a matter which is disregarded in the conventional tracing of circuits, which by common usage are followed in the opposite direction.

25 Resuming the circuit description, the removal of battery from conductor 499 by the energization of the release relay 401 of the control unit, Fig. 12, has the effect of making the trunk comprising conductors 365, 366 and 367 busy to other 30 calls originated at the finder unit in Fig. 11. For instance, if another call is made, and a circuit is closed for the guard relays 381, 382, etc., the guard relay 381 cannot energize because there is no battery potential on test conductor 367. The removal of battery potential from conductor 499 also makes busy all the other trunk lines such as 380, which normally terminate in the same control unit, and these trunks cannot be seized even though they are otherwise in idle 35 condition. The reason for this will of course be

clear. When any trunk such as 365-367 is taken for use, all the other trunks which use the same control unit must be made busy in order that the control unit may be reserved temporarily for the exclusive use of the call on trunk 365-367.

The placing of ground potential on conductor 498 by the energization of the release relay 401 of the control unit not only establishes a holding circuit in the manner described, but ground is also extended over the normal conductor 305 to the connector unit, where the calling line is made busy.

By the operations which have been described so far, the calling line has been extended by mechanism in the finder unit to an outgoing trunk line leading to a selector unit, where the trunk line normally or for the time being terminates in a control unit, as shown in Fig. 12. At the control unit the line and release relays 400 and 401 have energized, and the partially established connection is held by ground applied by the latter relay to conductor 499 and the holding circuit in which said conductor is included. Ordinarily the calling subscriber will now start to dial the digits in the number of the called line. It may happen, however, that for some reason the dialing is delayed. The receiver may have been accidentally knocked off, or the initiation of the call may even have been due to a short circuit on the line. In such a case it is desirable to release the partially established connection in order to prevent tying up the control circuit and the incoming trunk lines associated therewith. The timer including cams 493 and 494 is provided in order to take care of this situation, and its operation will now be briefly described.

As previously mentioned, the cams 493 and 494 are mounted on a common shaft which is rotating continuously at a constant speed. The rate of rotation may be such that the cams revolve once every half-minute. Cam 493 operates spring 497 shortly before cam 494 operates spring 498. If no dialing takes place, cam 493 will eventually operate spring 497, but without results. As soon as cam 493 passes its operative position, cam 494 operates spring 498 and thereby completes a circuit extending from ground at contact 417 by way of the left-hand winding of relay 402 and operated spring 498 to battery. Relay 402 is energized over this circuit and establishes a locking circuit for its other winding at spring 419. In addition, relay 402 opens the ground connection to conductor 499 and substitutes therefor a new ground connection through contact 496 and spring 497. The holding circuit therefor now includes the ground connection at spring 497.

After the lapse of one half-minute, cam 493 again operates spring 497 and thus opens the holding circuit. The gate operating magnet 371 accordingly immediately deenergizes and breaks the partially established connection. The opening of the line conductors is followed by the de-energization of relays 400, 401 and 402 in the control unit. The opening of the holding circuit also causes the immediate deenergization of line relay 306 but relay 307 is slow-acting and remains in operated position. When the relay 306 deenergizes, it connects ground to line conductor 301 at spring 308, and at spring 311 it connects the right hand winding of the cutoff relay 307 to line conductor 300. Accordingly the cutoff relay 307 remains energized over the calling line. The line relay cannot again energize due to the fact that

its circuit is open at contact 312 of the energized cutoff relay.

The line circuit is maintained in the described condition, with the cutoff relay 307 energized over the line, until the receiver is replaced at station A, or if the initiation of the call was caused by a short circuit on the line, until the short circuit is removed. When the line is cleared the cutoff relay 307 falls back, and if another call is made the circuits will then function in a normal manner. Although not shown in the drawings, arrangements may be provided for operating a signal whenever a line is locked out by energization of its cutoff relay under circumstances such as described. These arrangements may conveniently consist of a pilot relay connected in series with the right hand windings of each group of cutoff relays. Such circuits are well known and since their inclusion would occupy space otherwise required, they have not been shown herein.

It will be assumed now that the calling subscriber starts to dial promptly after removing the receiver, it being recalled that the act of removing the receiver has resulted in the extension of the calling line through the finder unit and by way of an outgoing trunk to a selector unit where the trunk terminates in the line relay of the control unit shown in Fig. 12. The line and release relays 400 and 401 of the control unit are energized. The number of the called subscriber is "212" and accordingly the first digit to be dialed is the digit "2". When the calling device is operated in accordance with the digit "2", two interruptions are produced in the calling line and the line relay 400 is deenergized twice. Release relay 401 remains operated due to its slow releasing characteristic.

At the first deenergization of line relay 400, the locking circuit of relay 402 is broken, if this relay should happen to have been energized, and a circuit is completed from ground by way of contact 413, contact 416, the winding of the slow-acting relay 403, and contact 423 to battery. Relay 403 accordingly energizes and remains energized in known manner until the dialing of the first digit is completed. At its contacts 420 and 421 relay 403 prepares a circuit for the first counting relay 405.

When the line relay energizes after the first interruption in the line circuit, it closes the previously prepared circuit for counting relay 405, said circuit extending from ground by way of contact 418 on the release relay 401, contact 414 of the line relay, contact 420, chain contacts of counting relays 409-406 in series, contact 421, and winding of counting relay 405 to battery. Upon energizing, relay 405 locks itself at contact 424, so that its circuit is no longer dependent upon the continued energization of relay 403, and at contact 425 prepares a circuit for the second counting relay 406.

When the line relay 400 deenergizes in response to the second interruption in the line circuit, it breaks the locking circuit of counting relay 405, but at the same time it completes a new holding circuit for said relay which includes also the second counting relay 406. This circuit extends from ground at contact 418 by way of normally closed contacts controlled by contact spring 414, contacts 423 and 425, winding of relay 406, and winding of relay 405 to battery. The completion of the last described circuit maintains the first counting relay 405 energized and also energizes the second counting

relay 406. Upon energizing, relay 406 prepares a holding circuit for itself at contact 426 and prepares a circuit for the third counting relay 407 at spring 427.

When the line relay 400 energizes following the second interruption, it breaks the circuit which includes the windings of relays 406 and 408 in series and therefore permits relay 405 to deenergize. At the same time, however, the line relay closes a holding circuit for relay 406, which extends from ground at 418 by way of 414, 420, chain contacts on relays 409, 408, and 407, contact 426, and winding of relay 406 to battery. The line relay 400 now comes to rest in energized position, with counting relay 408 energized.

Before continuing with the operation, it will be convenient to point out that the counting chain comprises five counting relays 405-409, inclusive, which are adapted to count the first five impulses in a series, and a transfer relay 410 by means of which the same five relays are enabled to count five additional impulses. By means of five relays and a transfer relay therefor a series of ten impulses may be counted. The manner in which this is done may be briefly explained, assuming that the digit "0" is dialed instead of the digit "2".

When the digit "0" is dialed, ten interruptions are produced in the line circuit and the line relay therefore deenergizes ten times. On the third, fourth and fifth deenergizations, counting relays 407, 408 and 409 are energized in the manner described in the case of relay 406. When relay 409 is energized, it prepares a circuit at contact 700 for relay 410, which accordingly is energized on the sixth deenergization of the line relay. Relay 410 locks itself at contact spring 703. When relay 410 energizes, it also breaks its initial energizing circuit and the circuit of relay 409 at contact 701, and relay 409 falls back, thus re-establishing the chain circuit which extends back through contact 421 of relay 403 to relay 405. When the line relay energizes following its sixth deenergization, therefore, relay 405 is energized. It will be understood that relay 410 is so adjusted that contact 703 closes before contact 701 opens. On the seventh deenergization of the line relay, relay 406 responds, and relays 407, 408 and 409 respond to the eighth, ninth, and tenth deenergizations, respectively. Following the tenth deenergization, the line relay comes to rest in energized position with relay 409 energized.

The transfer relay 410 not only drops relay 409 as described, but it operates to shift a control conductor from its normal association with the first five tens magnets into association with the second five tens magnets. For example, the second counting relay 406 is normally adapted to control the second tens magnet 432, but if the transfer relay 410 is energized, the second counting relay 406, now energized in response to the dialing of the digit "7" rather than the digit "2", is adapted to control the seventh tens magnet (not shown). The switching of the control circuit by the transfer relay 410 is accomplished at contact 702 in a manner which will be readily understood.

Resuming the description of the establishment of the connection which is being set up, the first digit "2" of the called number has been dialed, resulting in the energization of the second counting relay 406 in the control unit shown in Fig. 12. Relays 400, 401, and 403 of the control unit are also energized. When the dialing of the first digit is completed, the line relay no longer sends impulses to the slow-acting relay 403, and after

5 a short interval this relay falls back and completes a circuit for relay 404 extending from ground at contact 418, winding of relay 404, contacts controlled by spring 420 of relay 403, chain contacts of relays 409, 408, and 407, contact 426 of relay 406, and winding of relay 406 to battery. The above circuit maintains relay 406 energized. Relay 404 is energized in series with relay 406 and at contact 423 breaks the circuit which has been prepared for counting relay 407, also breaking the circuit of relay 403 at contact 423'. The purpose of these operations is to prevent the energization of relays 407 and 403 when the line relay 400 deenergizes upon the release of the control circuit. In addition, relay 404 closes a circuit for the relay 411 at contact 422.

10 15 20 25 30 35 40 45 50 55 60 65 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850 855 860 865 870 875 880 885 890 895 900 905 910 915 920 925 930 935 940 945 950 955 960 965 970 975 980 985 990 995 1000

Relay 411 is a so-called sequence relay, one of which is provided for each of the control units. The purpose of these relays is to insure that the control units function one at a time in controlling the operation of the selector unit. The drawing shows the sequence relay 412 associated with the second control unit and indicates by the dotted portion of conductor 705 the presence of additional sequence relays. If no other sequence relay such as 412, for example, is energized at the time the circuit of sequence relay 411 is closed at contact 422, relay 411 will energize over a circuit which extends from ground at contact 422, winding of relay 411, contacts controlled by spring 437, conductor 705, chain circuit including contacts such as 706 and 436 on all the sequence relays, and resistance 439 to battery. Upon energizing, the sequence relay 411 locks itself at contact 437 and breaks the chain circuit at contact 436, thus preventing any other sequence relay from operating. In addition to the foregoing, relay 411 completes a circuit extending from ground by way of contact 435, contact 702, contact 428, contact 429; and the winding of the tens magnet 432 to battery. Upon the closure of this circuit the tens magnet 432 is energized, thereby actuating the second tens bar and selecting the second group of outgoing trunk lines. It will be understood also that the operation of the tens bar is effective to raise the operating bar 486 in the special bank section, thus connecting the test conductors of the trunk lines in the second group to the units magnets 441, 442, 443, etc.

The energization of sequence relay 411 also is effective to close a test circuit including the units magnet 441, said circuit extending from ground at contact 422 by way of contact 434, conductor 449, the chain circuit including contacts of all the units magnets, conductor 489, winding of units magnet 441, rectifier 447, conductor 488, contact spring 487 in the special bank section, bar 455, conductor 462, contacts of gate-operating magnet 511 at the connector unit, Fig. 13, contacts of relay 510, conductor 512, contact 627 of the release relay 601 of the connector control unit, Fig. 14, and through resistance 628 to battery. It will be noted that the above circuit is completed only in the event that relay 601 of the connector control unit is deenergized, as otherwise the connection to battery through resistance 628 will be broken. At the same time that the above circuit is closed, similar circuits are completed through all the other units magnets, such as 442, 443, etc., which are associated with idle trunk lines, that is, trunk lines which have their test conductors connected to battery at the control circuits in which they terminate.

It follows, therefore, that all of the units magnets which are associated with idle trunk lines start to energize responsive to the operation of the sequence relay 411. Assuming now that the first trunk line is idle, relay 601 of the connector control unit, Fig. 14, being deenergized, the units magnet 441 will operate and will establish a locking circuit for itself at contact 446, at the same time breaking the chain circuit and preventing any of the other units magnets from energizing. In addition, the units magnet 441 places ground at contact 445 on the test circuit including bar 455, thus making the selected idle trunk line busy. The resistance 628 at the connector control unit, Fig. 14, is high enough to prevent excessive current flow. It will be understood also that the units magnet operates the first units bar, thereby preparing for operation all blocks such as 466 in the first horizontal row.

In addition to the operations described in the preceding paragraph, the units magnet 441 completes a circuit for relay 470, extending from ground at contact 444, conductor 448, contact 438 of relay 411, conductor 440 and winding of relay 470, to battery. Relay 470 accordingly energizes and at contact 495 removes the short circuit from the low impedance left hand winding of gate-operating magnet 472, thereby connecting this winding in the holding circuit. The holding circuit is grounded at contact 415 of the release relay 401 and supplies current over conductor 499 for maintaining the gate-operating magnet 371, Fig. 11, and the line and cutoff relays of the calling line in energized position. The current supplied over the holding circuit now flows through the left hand winding of gate-operating magnet 472 and the magnet is energized sufficiently to close its locking contact 473. The right hand winding of the gate-operating magnet is thus connected to the holding circuit and the magnet becomes fully energized, raising the gate and simultaneously lifting the block 466 and the operating bar 484.

When the gate-operating magnet 472 energizes, the actuation of contact spring 474 and the make before break contacts associated therewith disconnects the incoming test conductor 367 from that part of the holding circuit which extends over conductor 499 to ground at the control unit and at the same time extends said conductor 367 by way of contact 474, contact 469, spring 465, and spring 458 to bar 455, which is now connected to ground by way of spring 487 and contact 445 of units magnet 441. This establishes a temporary holding circuit which maintains the connection until the line and release relays in the connector control unit have had time to energize, as will be explained shortly. The right hand winding of gate-operating magnet 472 receives current from the holding circuit through contact 473, which maintains the magnet energized. It will be understood that contact spring 474 and associated contacts should be so adjusted that conductor 367 is not disconnected from conductor 499 until the gate is substantially fully operated, which will insure that springs 465 and 458 are actuated.

The energization of gate magnet 472 also shifts the contacts 475 and 476, whereby the line conductors 365 and 366 of the incoming trunk are disconnected from the line relay 400 of the control unit and are extended by way of contacts 467 and 468, springs 463 and 464, springs 456 and 457, bars 453 and 454, outgoing trunk conductors

460 and 461, contacts 561 and 562 of gate-operating magnet 571, Fig. 13, conductors 510 and 511, and through the windings of the line relay 600 of the connector control unit, Fig. 14, to battery and ground, respectively. The line relay 600 is accordingly energized over the calling line and closes a circuit for the slow-acting release relay 601. Upon energizing, the latter relay disconnects the incoming test conductor 512 from its path to battery through resistance 628 and connects it instead to ground. The grounding of conductor 512 establishes a holding circuit extending back over conductors 512 and 462 to the selector unit, where conductor 462 is now connected to conductor 367, as previously explained. This holding circuit maintains the connection after the temporary circuit to ground at the units magnet 441 is broken by the release of the selector control unit, Fig. 12.

The disconnection of incoming trunk conductors 365 and 366 from the line relay 400 of the control unit by the operation of gate magnet 472 allows the line relay to deenergize and break the circuit of slow-acting release relay 401, which falls back also after a short interval and breaks the circuit of relays 404 and 406. On deenergizing, relay 406 breaks the circuit of tens magnet 432, which deenergizes and allows the associated tens bar to restore, thereby also restoring the operating bar 486 in the special bank section. Relay 404, on deenergizing, opens the circuit of units magnet 441, which deenergizes and allows the operated units bar to restore at the same time as the operated tens bar. The units magnet also opens the circuit of relay 470, which accordingly deenergizes. At the same time that relay 404 opens the circuit of the units magnet it opens the circuit of sequence relay 411. This relay is made slow to deenergize in order to allow time for the tens and units magnets and their associated selecting bars to restore. After a short interval relay 411 deenergizes and closes the sequence relay chain circuit at contact 438. If a call is waiting on another control unit the associated sequence relay can now energize.

When the release relay 401 falls back, its circuit having been broken by the line relay 400, it not only opens the circuit of relays 404 and 406, but also disconnects ground from conductor 499 and connects this conductor to battery at contact 415. Battery potential is thus applied by way of contacts of the now deenergized relay 470 to the test conductors of all the idle trunk lines which normally terminate in the control unit under consideration, thereby placing such trunk lines in selectable condition. Trunk line 380, for instance, may now be selected, but trunk line 365-367 of course remains unaffected since the gate magnet 472 is in energized position and the trunk conductors are disconnected from the control unit.

The calling line has now been extended to the line relay 600 of the connector control unit, Fig. 14, and relays 600 and 601 are energized. When the calling subscriber dials the second digit in the called number, or the digit "1," a single interruption is produced in the line circuit and the line relay momentarily deenergizes once, release relay 601 remaining in operated position due to its slow-releasing characteristic.

When the line relay falls back it closes a circuit for slow-acting relay 610 by way of contact 625, contact 626, contact 640, and winding of relay 610 to battery. Relay 610 energizes and at contact 648 closes a circuit for slow-acting relay

619, the latter relay locking over a circuit which extends from ground at contact 624 by way of conductor 633, contact 666, contact 655, and winding of relay 619 to battery. The energization of relay 619 is of no effect at the moment. Relay 610 also prepares a circuit for the first counting relay 612 of the tens group at contacts 644 and 646. The other circuit changes caused by relay 610 are of no effect for the present.

When the line relay energizes following its momentary deenergization, it closes a circuit for counting relay 612, said circuit extending from ground at contact 624, contact 623, conductor 634, contact 650, contact 646, chain contacts of counting relays 616, 615, 614, and 613, contact 644, and winding of relay 612 to battery. On energizing, relay 612 locks itself in the above circuit at contact 653, whereby its continued energization is made independent of contact 644 of relay 610. The line relay 600 being at rest now in energized position, the slow-acting relay 610 deenergizes and completes a circuit for relay 611, extending from grounded conductor 633 by way of winding of relay 611, contacts controlled by spring 646, chain contacts of counting relays 616—613, contact 653 and winding of counting relay 612 to battery. Current flow over this circuit energizes relay 611 and maintains relay 612 energized. Relay 611 disconnects control conductor 632 from the counting relays of the tens group at contact 649, thereby preventing any of these relays from responding to the next digit, prepares a locking circuit for itself at contact 650, which prevents it from deenergizing when relay 610 energizes again, and prepares for the operation of the first counting relay 608 of the units group by closing contact 651.

The foregoing completes the description of the operations which take place in response to the dialling of the second digit of the called number. The digit dialled being the digit "1," only the first counting relay 612 is energized. The operation of the counting relays responsive to the dialling of other digits has been explained in connection with the selector control unit, Fig. 12.

The calling subscriber may now dial the last digit of the called number, or the digit "2," thereby causing two momentary deenergizations of the line relay 600. Relay 601 again remains in operated position during momentary interruptions in its circuit due to falling back of the line relay.

On the first deenergization of the line relay a circuit is closed for relay 610 over the path previously traced and this relay again energizes, remaining in operated position until the line relay comes to rest in energized position after completing its response to the last digit. The operation of contacts 644 and 646 are of no effect at this time, relays 611 and 612 remaining locked up by way of contact 650. At contacts 645 and 647, relay 610 prepares a circuit for the first counting relay 608 of the units group.

When the line relay 600 energizes following its first deenergization, a circuit is completed from ground at contact 624, contact 623, conductor 634, contact 647, contact 651, chain contacts of counting relays 604, 605, 606, and 607, contact 645, and winding of the first counting relay 608 of the units group to battery. On energizing, relay 608 locks itself in the above traced circuit at contact 667, and at contact 668 prepares a circuit for the second counting relay 607.

When the line relay 600 deenergizes the second time, it breaks the initial energizing circuit 75

of counting relay 608; but at the same time it closes a new circuit through relays 607 and 608, extending from ground at contact 624, contacts controlled by spring 623, conductor 632, contact 639, contact 668, winding of relay 607, and winding of relay 608 to battery. Current flow over this circuit energizes relay 607 and maintains relay 608 energized. Relay 607, on energizing, prepares a holding circuit for itself at contact 637, and at contact 669 prepares a circuit for counting relay 606.

When the line relay 600 energizes following its second deenergization, it completes the holding circuit of relay 607 to maintain this relay energized, and at the same time it breaks the previously described circuit which includes relay 607 and relay 608 in series. Relay 608 accordingly deenergizes.

The line relay comes to rest in energized position and after a short interval, therefore, relay 610 deenergizes, closing a circuit for relay 609 extending from the grounded conductor 633 by way of the winding of relay 609, contacts controlled by spring 647, contact 651, chain contacts of counting relays 604, 605, and 606, contact 637, and winding of counting relay 607 to battery. This circuit serves to maintain relay 607 energized and energizes relay 609. On energizing, relay 609 disconnects the control conductor 632 from the counting relays of the units group at contact 639 and opens the circuit of relay 610 at contact 640. These operations render further dialling ineffective, and also prevent any relay operations upon the deenergization of the line relay when the control unit is subsequently released. Relay 609 also prepares a busy signalling circuit at contact 642.

In addition to the foregoing, relay 609 closes a circuit for the sequence relay 621, which extends from ground at contact 643 by way of contact 670, winding of relay 620, winding of relay 621, contacts controlled by spring 664, conductor 675, chain contacts of all sequence relays, including contact 663 of relay 621, and resistance 665 to battery. The above circuit may, of course, be open at one of the other sequence relays such as relay 622, in which case the call under consideration will have to wait. Assuming, however, that no other sequence relay is energized, the circuit is completed as described when relay 609 energizes, and is effective to energize relays 620 and 621. The former relay breaks the locking circuit of relay 619. This relay is slow-acting and does not restore immediately.

When relay 621 energizes, it locks itself at contact 664 and at contact 663 it opens the chain circuit, thereby preventing any other sequence relay from energizing. Relay 620 remains energized in series with relay 621.

The energization of sequence relay 621 closes a circuit for the first tens magnet 531 of the connector unit, Fig. 13, as follows: ground at contact 643, contact 670, contact 662, contact 676 of transfer relay 617; contact 652 of counting relay 612, conductor 71, and winding of tens magnet 531 to battery. On energizing, the tens magnet actuates the first tens bar, which selects the first sub-group of lines terminating in the connector unit, and also raises the operating bar 550 in the special bank section, thereby connecting the test conductors of the lines in this sub-group to conductors leading to contacts of the units magnets 541, 542, 543, etc. At the same time that relay 621 closes the circuit for the tens magnet 532, it closes a parallel circuit for the

units magnet 542, extending by way of contact 661, conductor 635, contact 638 of transfer relay 603, contact 641, contact 636 of counting relay 607, conductor 662, and winding of units magnet 542 to battery. On energizing, units magnet 542 actuates the second units bar of the connector unit, thereby selecting the second line in the selected sub-group. At its contact 553, the units magnet 542 also connects the test conductor of the selected line to test conductor 673.

At the same time that the sequence relay 621 closes the previously described circuits for the tens and units magnets at contacts 662 and 661, it connects up the test relay 618 at contact 660. Assuming now that the selected called line is idle, there will be a battery potential on the associated test conductor (through the winding of the cutoff relay), and the following circuit is established as soon as the units magnet 542 closes its contact 553: ground at contact 654 of relay 619, Fig. 14, winding of test relay 618, contact 660, conductor 673, contact 553, Fig. 13, conductor 552, spring 551, bar 546, private normal or test conductor 505, winding of line relay 314, Fig. 11, and winding of cutoff relay 315 to battery.

The test relay 618 of the connector control unit is energized over the above circuit and locks itself to the grounded conductor 633 at contact 651. Relay 618 also places direct ground on the test conductor of the called line at contact 658, which makes the called line busy to other calls. The line relay 314 and the cutoff relay 315 are energized, and clear the line conductors 500 and 501 of their normal battery and ground connections via conductors 504 and 503.

When the test relay 618 of the control unit energizes it also closes a circuit which extends from ground at contact 659 by way of conductor 674 to relay 570, which energizes and removes the short circuit from the low impedance right hand winding of the gate-operating magnet 571 of the connector unit. By this operation the right hand winding of magnet 571 is inserted in the previously described holding circuit extending from the connector control unit back to the selector unit over conductors 512 and 462, with the result that magnet 571 is energized by current flow over the holding circuit and closes its locking contact 564. The left hand winding of magnet 571 is thus connected to the holding circuit, and the magnet becomes fully energized, raising the gate and thereby lifting the block 533 and the operating bar 540. Contact 563 of the magnet 571 having closed, a temporary holding circuit is established which extends from ground at contact 658 of the test relay 618 by way of conductor 673, contact 553, conductor 552, spring 551, bar 546, spring 549, spring 536, contact 539, and contact 563 to test conductor 462 of the trunk line in use. The remainder of the holding circuit is the same as previously traced. Contact spring 563 and its associated make before break contacts are adjusted so that they will not disconnect conductor 512 coming from the control unit until the gate is substantially fully operated, or sufficiently so that springs 536 and 549 have been closed against contact 539 and bar 546, respectively.

When the gate-operating magnet 571 energizes, it switches over its contacts 561 and 562, thereby disconnecting the line conductors 460 and 461 of the incoming trunk line from conductors 510 and 511 extending to the control unit and connecting them instead to conductors 513 and 514 extending to the battery feed unit which

is associated with the incoming trunk line. The line relay 520 is accordingly energized over the calling line and closes a circuit for the slow acting release relay 521. On energizing, the latter relay completes the final holding circuit, which extends from ground at contact 525 by way of conductor 517 and contact 563 of magnet 571 to test conductor 462, and continues over the latter conductor back to the selector and finder units as previously traced. A branch of the holding circuit extends to the test conductor of the called line by way of contact 539, spring 536, spring 549 and bar 546. Ground on this branch circuit maintains the called line busy and holds up the line and cutoff relays 314 and 315 after the connector control unit has been released.

It will be recalled now that the locking circuit of the slow-acting relay 619 in the connector control unit was broken by relay 620 when the latter relay energized in series with the sequence relay 621. The energization of the sequence relay 621 is followed in succession by the energization of the tens and units magnets, the energization of the test relay 618, the energization of relay 570, and the energization of the gate-operating magnet 571. These successive operations take only a fraction of a second and relay 619 is slow enough so that it does not restore until after the gate-operating magnet has energized, or until after the incoming trunk has been disconnected from the control unit. The adjustment is not critical and relay 619 may be slower than mentioned, but it should at least stay in operated position as long as stated in order to prevent the connection of busy tone to the incoming trunk before the trunk is switched to the battery feed unit.

On deenergizing, relay 619 breaks the circuits of the energized tens and units magnets 531 and 542 at contact 670. The tens magnet deenergizes and permits the operated tens bar to restore, thereby restoring the operating bar 550 in the special bank section. The units magnet deenergizes and permits the operated units bar to restore, also disconnecting conductor 673 at contact 553. In addition to the foregoing, the deenergization of relay 619 breaks the circuit of relays 620 and 621, which deenergize. The latter relay is slow-acting, however, and stays in operated position momentarily, thus affording a short interval of time in which the tens and units bars are able to restore properly. When relay 621 falls back it closes the sequence relay chain circuit at contact 663. Any other sequence relay such as 622 can now energize, if there is a call waiting on the associated control unit.

When the trunk conductors 460 and 461 are disconnected from conductors 510 and 511 by the operation of the gate magnet 571, the line relay 600 deenergizes, breaking the circuit of the release relay 601, which falls back after a short interval. The deenergization of relay 601 removes ground from conductor 633, which permits relays 618, 611 and 609 and the counting relays 612 and 607 to deenergize, the deenergization of relay 618 being followed by the deenergization of relay 570. At the same time, at contact 627 of relay 601, the test conductor 512 is disconnected from ground and is connected to battery by way of resistance 628. This operation removes the artificial busy condition from trunks such as 555 associated with the control unit and renders such trunks selectable.

Returning now to the connection under discussion, the calling line has been extended to the

line relay 520 of the battery feed unit, where relays 520 and 521 are energized. The other side of the battery feed unit has been extended by way of conductors 515 and 516, contacts 537 and 538, springs 533 and 534, springs 547 and 548, and line bars 544 and 545 to the conductors 500 and 501 of the called line. The release relay 521 being energized, the indicated source of ringing current GEN. is now connected to conductor 516 by way of contacts 521 and 528, and the bell at station B is rung in the usual manner.

The return path for the ringing current includes conductor 515 and the lower winding of the ring cutoff relay 523; and when the receiver is removed at station B, relay 523 is energized in well known manner and locks itself at contact 527. At contacts 526 and 528, relay 523 opens the ringing circuit and completes the talking circuit. The transmitter at the called station B is supplied with current through the windings of the back bridge or battery feed relay 522, while the transmitter at the calling station A is supplied with current through the windings of the line relay 520. The line relay is maintained energized by current flow over the calling line and maintains the established connection through the medium of the release relay 521. The talking circuit includes the condensers 529 and 530 at the battery feed unit and is shown in heavy lines.

At the end of the conversation the calling and called subscribers will replace their receivers. When the receiver is replaced at the calling station A, the line circuit is opened and the line relay 520 is deenergized, breaking the circuit of the release relay 521. After a short interval relay 521 falls back, breaking the locking circuit of relay 523 at contact 524. Relay 523 accordingly deenergizes. Relay 521 also opens the holding circuit at contact 525, whereupon all the apparatus involved in the connection is released and restored to normal. The restoring operations will be readily understood but may be gone over briefly. Beginning at the called end of the connection, the removal of ground from the test conductor of the line of station B permits the line and cutoff relays 314 and 315 to restore, assuming the receiver has been replaced, thus placing the line in normal condition. At the connector unit the deenergization of the gate magnet 571 permits the gate to restore, thereby restoring the block 533 and the operating bar 540. At the selector unit, the deenergization of gate magnet 472 permits the associated gate to restore, thereby restoring the block 466 and the operating bar 484. At the finder unit, gate magnet 371 deenergizes, restoring the block 325 and operating bar 322. Removal of ground from the test conductor of the line of station A permits the line and cutoff relays 306 and 307 to deenergize, placing the line in normal condition. All the apparatus is therefore restored and placed in condition for another call.

In the foregoing description it was assumed that the line of station B was idle when called. A brief explanation will now be given of the operations which take place if the called line is busy. The called line is tested for its idle or busy condition when the test relay 618 of the connector control unit, Fig. 14, is connected to the test conductor of the called line by the operation of the sequence relay 621. If the called line is idle there is a battery potential on the test conductor and the test relay 618 is energized, with results already described. If the called line is busy, there is a ground potential on the test conductor and

the test relay 618 cannot energize. After a short interval relay 619, the circuit of which is opened by relay 620 at the time the sequence relay 621 is energized, deenergizes and opens the test circuit at contact 654. At contact 670, relay 619 breaks the circuits of the tens and units magnets and the circuit of relays 620 and 621, with results previously described. At contact 656 relay 619 connects a source of busy signalling current to conductor 511, thus transmitting a busy signal to the calling subscriber in the well known manner. The calling subscriber will accordingly hang up his receiver. Line relay 600 of the control unit therefore deenergizes, followed by the deenergization of the release relay 601. The latter relay removes ground from conductor 633 at contact 624 and breaks the holding circuit at contact 627, whereupon the apparatus is restored to normal as previously described.

In case the calling subscriber fails to dial after his line has been extended to the connector control unit, or if the calling subscriber should fail to hang up this receiver after receiving the busy signal, the connection is released by means of relay 602 and the timer comprising cams 493 and 494, Fig. 12. The operation of this equipment has been described in connection with the selector control unit shown in Fig. 12.

The description of the operation of the system has now been completed. It will be understood that the invention is not limited to a system of the size described, but is adapted for use with a system of any size. For example, a one hundred line system can be built, using a single finder unit and a single connector unit, no selector unit being employed. On the other hand, the capacity may be expanded to any desired extent by the insertion of additional orders of selector units. It will be understood also that where specific values and quantities have been given this has been done merely for convenience in explaining one typical embodiment of the invention. As an example may be mentioned the fact that the switching units have been described as comprising ten bank sections, although they may each have fifteen or twenty bank sections. Or the switching units at a certain stage may have a certain number of bank sections, whereas the units at another stage may have a different number of bank sections. In view of these considerations it will be understood that the invention is not restricted to the precise apparatus and system shown and described herein, but comprehends various modifications, limited only by the scope of the appended claims.

I claim:

1. In an automatic telephone system, a group of test conductors each adapted to have different potentials placed thereon depending on the idle or busy condition of the associated lines, a group of selecting magnets, means for closing circuits for all said magnets simultaneously, each magnet circuit including one of said test conductors and a common conductor, and a rectifier connected in series with each magnet and its associated test conductor to prevent current flow from one test conductor to another through two magnets in series and a section of said common conductor.

2. In an automatic telephone system, a cross-bar switching device including tens and units selecting bars, magnets for operating said units bars, means responsive to the operation of any tens bar for closing a plurality of circuits in which the units magnets are connected in series, respectively, with the test conductors of a sub-

group of lines, and means including chain contacts on said magnets for energizing the magnet connected with the first idle line and for preventing the energization of the remaining magnets.

3. In an automatic telephone system, a cross-bar switch, tens and units magnets for preparing said switch for operation, a selective control unit including a digit register, means responsive to the operation of said register for energizing one of said tens magnets, and means for simultaneously closing circuits for said units magnets, the circuit of each units magnet including a contact closed by the operated tens magnet and a contact closed responsive to the operation of the control unit.

4. In an automatic telephone system, a cross-bar switch, a trunk line extending to said switch, tens and units magnets controlled over said trunk line to prepare a plurality of contact sets in said switch for operation to extend said trunk line, a trunk magnet for operating said contact sets, means for energizing said trunk magnet, and a holding circuit for said magnet including the said contact sets and a contact on the units magnet in use.

5. In an automatic telephone system, a cross-bar switching mechanism, a trunk line incoming to said mechanism, a holding circuit including the test conductor of said trunk line, means for setting up a flow of current over said circuit, selective means controlled over said trunk line for preparing said mechanism for operation to extend said trunk line, an operating magnet for said mechanism, means effective upon the completion of the operation of said selective means for connecting said magnet in series with said holding circuit, whereby said magnet is energized by the previously established current flow over said holding circuit, a locking circuit for said magnet, and means for maintaining said magnet energized over the extended trunk line.

6. In an automatic telephone system, a cross-bar switch, a selection control unit, a plurality of trunks normally terminating in said control unit, a switch operating magnet individual to each trunk, each magnet having a normally short-circuited winding in series with the test conductor of the associated trunk, means for controlling said unit over any trunk which is taken for use, and means effective upon the completion of the operation of said unit for removing the short circuits from all said magnet windings, whereby the magnet individual to the trunk in use is energized.

7. In an automatic telephone system, a cross-bar switch, a trunk line extending to said switch and normally terminating in a control unit, means for operating said unit over said trunk line to prepare a plurality of contact sets in said switch for operation to extend said trunk line, a magnet for actuating said contact sets, and switching contacts on said magnet for disconnecting said trunk line from said control unit and for extending it to one of said contact sets.

8. In an automatic telephone system, a cross-bar switch, an operating magnet for said switch, a trunk line incoming to said switch and comprising two normally disconnected sections, one section extending to a control unit and the other section extending by way of a battery feed unit to multiply connected contacts of said switch, and contacts on said magnet for disconnecting the first section from said control unit and for connecting said sections together.

9. In an automatic telephone system, crossbar switches at selector and connector stages in said system, each switch including common tens and units selecting magnets and trunk operating magnets individual to the trunks terminating in such switch, means including said magnets for building up a connection including serially related trunk lines normally terminating at said stages, respectively, means for maintaining the connection comprising the trunk magnets individual to the trunks in use, each magnet being effective to hold closed a plurality of sets of switch contacts and a set of contacts outside the switch, and a relay energized over the connection to maintain said trunk magnets energized.

10. In an automatic telephone system, a selector stage comprising crossbar switches, each switch terminating a plurality of incoming trunk lines, a plurality of groups of trunk lines outgoing from said switches, said outgoing trunk lines being multiplied to non-corresponding contact sets in the different switches, means in each switch including selecting bars controlled over any incoming trunk for selecting a group of outgoing trunks and the first idle trunk in the selected group, and means in each switch individual to the incoming trunk in use for extending it to a selected outgoing trunk.

11. In an automatic telephone system, two crossbar switches, contact sets in each switch assigned to a plurality of sub-groups of lines, a group of trunk contacts in each switch, trunk lines connecting the trunk contacts in one switch with the trunk contacts in the other switch, means in one switch for selecting a sub-group of the lines terminating therein and a particular line in the selected sub-group, means effective upon the completion of such selection for selecting the first idle one of said trunk lines, and means effective upon the completion of the second selection for connecting the selected line and trunk line.

12. In a telephone system, a group of subscribers' lines, tens and units marking relays associated with said group of lines, a line relay for each line, means responsive to the energization of any line relay for energizing the tens relay of the sub-group to which the calling line belongs, a circuit for the corresponding units relay prepared by the energized line relay, and means controlled by the energized tens relay for simultaneously closing points in the circuits of all said units relays, whereby the units relay corresponding to the calling line is energized.

13. In a telephone system, a group of subscribers' lines, a cross bar finder switch having access to said lines, tens and units selecting magnets controlling the operation of said switch in response to calls on said lines, test conductors for said lines, and means responsive to the operation of any tens magnet for connecting the units magnets, respectively, to the test conductors of a plurality of lines.

14. In a telephone system, a group of subscribers' lines, a line and cut-off relay for each line, a cross bar finder switch having access to said lines, tens and units magnets controlling the selecting operation of said switch, test conductors for said lines, contacts on each line relay for energizing one of said tens magnets and for connecting the test conductor of the associated line to its cut-off relay, and means operated by the energized tens magnet for connecting said units magnets to the test conductors of a plurality of lines including the calling line.

15. In a telephone system, a group of subscribers' lines, a cross bar finder switch having access to said lines, tens and units magnets for controlling the selecting operation of said finder, test conductors for said lines on which test potentials are placed when the lines are calling, means operated by a tens magnet in response to a call for connecting said units magnets to the test conductors of a plurality of lines including chain contacts on said units magnets for preventing the energization of more than one units magnet in case more than one line of said plurality is calling.
16. In a telephone system, a group of subscribers' lines, a cross bar finder switch having access to said lines, tens and units magnets for controlling the selecting operation of said finder, test conductors for said lines on which test potentials are placed when the lines are calling, means operated by a tens magnet in response to a call for connecting said units magnets to the test conductors of a plurality of lines including the calling line, and means including chain contacts on said units magnets for preventing the energization of more than one units magnet in case more than one line of said plurality is calling.
17. In a telephone system, a group of subscribers' lines, a cross bar finder having access to the said lines, tens and units magnets controlling the selecting operation of said finder, test conductors for said lines, means responsive to a call on one of said lines for energizing a tens magnet and a units magnet, the energizing circuit of the units magnet including the test conductor of the calling line, and means controlled by contacts on the energized units magnet for placing a test potential on the test conductor over which it is energized.
18. In a telephone system, a group of subscribers' lines, a cross bar finder switch having access to said lines, individual line relays for said lines, tens and units magnets controlling the selecting operation of said switch, circuits for said tens magnets directly controlled by said line relays, circuits for said units magnets jointly controlled by said line relays and by said tens magnets, and means comprising tens selecting bars operated by the tens magnets through the medium of which said tens magnets exercise control over said circuits.
19. In a telephone system, a group of lines, each including a test conductor, a switching device having access to said lines and including a plurality of relays, means including conductors individual to said relays for connecting the same simultaneously to the test conductors of a plurality of said lines, and a rectifier connected in series with each of said individual conductors to limit the current flow therein to one direction only.
20. In a telephone system, a group of trunk lines, each trunk line including a test conductor, means for selecting idle trunks, said means including an individual relay per trunk, individual conductors connecting said relays with the test conductors of their respective trunks, and a rectifier connected in series in each individual conductor to limit current flow therein to one direction only.
21. In a telephone system, a selector switch, a finder switch for extending a calling line to said selector switch, a magnet for maintaining the finder in operated position, an operating magnet for the selector, and a circuit for energizing the selector operating magnet in series with said finder magnet.
22. In a telephone system, an automatic switch, switching means for extending a calling line to said automatic switch, a cut-off relay for the calling line, an operating magnet for the said automatic switch, and a circuit over which current is supplied through said cut-off relay to energize said operating magnet.
23. In a telephone system, an automatic switch, switching means for extending a calling line to said switch, a holding circuit for said switching means, an operating magnet for said switch included in said holding circuit and normally short-circuited, means controlled over the calling line for governing the selecting operation of said switch, and means effective upon the completion of the selecting operation for removing the short circuit from said operating magnet, whereby said magnet is energized over said holding circuit.
24. In an automatic telephone system, a cross bar switch, two orders of serially related contact sets in said switch, means controlled over a calling line for selecting a contact set in each order for operation, a magnet for operating the selected contact sets, and contacts on said magnet for extending the calling line through the switch by way of the operated contact sets.
25. In an automatic telephone system, a cross bar switch, a plurality of trunk lines terminating in said switch, two orders of serially related contact sets in said switch, means common to said trunk lines and controllable over any trunk line to select a contact set of each order for operation, and a magnet for each trunk line for operating a pair of selected contact sets and for maintaining them operated, said magnets constituting the only magnets in the switch which are individual to the trunk lines, respectively.
26. In an automatic telephone system, a cross bar switch, a plurality of trunk lines incoming to said switch, tens and units magnets common to all said trunk lines for controlling the selecting operations of said switch, control units each common to a plurality of said trunk lines for controlling the operation of said magnets, and means including sequence relays individual to the control units for causing two or more active control units to exercise their control over the magnets in succession.
27. In an automatic telephone system, a cross bar switch, a plurality of trunk lines incoming to said switch, contact sets in said switch, means including one of said trunk lines and a pair of said contact sets for connecting a calling and called line, means controlled over the calling line in response to the dialling of two digits in the number of the called line for selecting the particular contact sets to be operated, means for simultaneously operating the selected contact sets, battery feed means for the calling and called lines, and means for connecting said battery feed means to the calling and called lines simultaneously when the selected contact sets are operated.
28. In a cross bar finder switch, tens and units selecting bars, tens and units magnets for actuating said bars, respectively, means responsive to a call on a line accessible to said finder for energizing a tens magnet and a units magnet, means responsive to said call for preventing the energization of a second tens magnet or units magnet by another call, serially related contact sets selected by the actuated tens and units bars, respectively, and means common to all said bars

for operating the selected contact sets to extend the calling line.

29. In a cross bar finder switch, a plurality of selecting bars each individual to a sub-group of lines, actuating magnets individual to said bars, respectively, means responsive to a call on a line in one of said sub-groups for energizing the corresponding magnet, said means including a chain circuit through serially related contacts on all of said magnets, and means including the said contacts on the energized magnet for opening said chain circuit and for maintaining the magnet energized independent thereof.

30. In a cross bar finder switch, a plurality of selecting bars each individual to a sub-group of lines, actuating magnets individual to said bars, respectively, means responsive to calls on lines in two different sub-groups for starting the energization of the two corresponding magnets, and means including contacts operated by one of the said two magnets for locking itself and for opening the initial energizing circuit of the other magnet, whereby the latter magnet is prevented from completing its energization.

31. In a cross bar finder switch, tens and units selecting bars, tens and units magnets for actuating said bars, respectively, a third set of bars equal in number to the tens bars, means responsive to a call for operating a tens bar, said means including one of said tens magnets, means controlled by the energized tens magnet for operating the bar in said third set which corresponds to the operated tens bar, and circuits for all said units magnets prepared by operation of said third set bar.

32. In a cross bar finder switch, tens and units selecting bars, tens and units magnets for actuating said bars, respectively, means responsive to a call on a line accessible to said finder for energizing the corresponding tens and units magnets, locking circuits for the energized magnets, serially related contact sets selected by the actuated tens and units bars, respectively, means including a common operating magnet for closing the selected contact sets to extend the calling line, and means operated in timed relation with the energization of said operating magnet to open said locking circuits to release the actuated selecting bars.

33. In a cross bar finder switch, a plurality of trunking sections, each individual to a trunk line, tens and units line selecting bars common to said trunking sections, means responsive to a call on a line accessible to said finder and including the corresponding tens and units bars for selecting sets of serially related contacts in each of said trunking sections, means including guard relays individual to said trunk lines, respectively, for selecting an idle trunk line responsive to said contact selection, means including a magnet individual to the selected trunk line for closing the selected contacts in the associated trunking section to connect the calling line to the selected trunk line, and means controlled by the guard relay individual to the selected trunk line for restoring the actuated tens and units bars.

34. In an automatic telephone system, a cross bar selector switch, trunk lines incoming to said switch, groups of trunk lines outgoing from said switch, tens bars common to said incoming trunk lines for selecting groups of outgoing trunk lines, means controlled over any incoming trunk line for actuating one of said tens bars to select a desired group of outgoing trunk lines, units bars common to said incoming trunk lines for select-

ing idle outgoing trunk lines, means responsive to the completion of group selection for actuating a units bar to select an idle trunk line in the selected group, means including a pair of serially related contact sets for connecting the incoming trunk line in use with the selected outgoing trunk line, and means including a magnet individual to the incoming trunk line in use for closing both said contact sets simultaneously.

35. In an automatic telephone system, a cross bar switch, a plurality of trunk lines incoming to said switch, a plurality of groups of trunk lines outgoing from said switch, a plurality of intermediate trunk lines, selecting bars common to said incoming trunk lines and effective when operated in pairs to select intermediate trunks which are common to a particular outgoing trunk and individual, respectively, to said incoming trunks, means including a register controlled over any one of said incoming trunks for actuating a pair of said bars, means including a pair of serially related contacts for connecting the incoming trunk in use over the selected intermediate trunk individual thereto to the particular outgoing trunk associated with such intermediate trunk, and means including an operating element individual to the incoming trunk in use for closing said contacts.

36. In an automatic telephone system, a cross bar switch, a group of trunk lines incoming to said switch, a plurality of groups of trunk lines outgoing from said switch, groups of primary contact sets in said switch equal to the product of the number of incoming trunk lines times the number of groups of outgoing trunk lines, secondary contact sets in said switch equal to the product of the number of incoming trunk lines times the number of trunk lines in a group of outgoing trunk lines, means responsive to a digit transmitted over an incoming trunk line for selecting the groups of primary contact sets identified with a particular group of outgoing trunk lines, testing means for selecting the secondary contact sets identified with an idle trunk line of the selected group, means individual to the incoming trunk line in use for actuating the particular group of the selected groups of primary contact sets and the particular contact set of the selected secondary contact sets which are identified with the incoming trunk line in use, and connections between the actuated secondary contact set and an actuated primary contact set whereby such incoming trunk line is extended to the selected idle outgoing trunk line.

37. In an automatic telephone system, a cross bar switch, a plurality of trunk lines incoming to said switch, a plurality of groups of trunk lines outgoing from said switch, a digit register common to said incoming trunk lines, means responsive to the registration of a digit transmitted to said register over one of said incoming trunk lines for selecting a group of outgoing trunk lines, testing means for selecting an idle outgoing trunk line in the selected group, a group of primary contact sets in said switch identified with the selected group, a secondary contact set identified with the selected trunk line in said group, means including a magnet individual to the incoming trunk line used in operating said register for actuating all said contact sets, and connections between said secondary contact set and the primary contact set associated with the selected trunk line, whereby the incoming trunk in use is extended to the selected outgoing trunk line by operation of said contact sets.

38. In an automatic telephone system, a cross bar switch, a plurality of trunk lines incoming to said switch, a register for registering a digit transmitted over one of said trunk lines, tens and units selecting bars, means for actuating a tens bar under control of said register, means for automatically actuating a units bar, serially related contact sets in said switch selected by the actuated tens and units bars, respectively, means individual to the trunk line in use for closing the selected contact sets, and an outgoing trunk line connected through said contact sets to the incoming trunk line in use.

39. In an automatic telephone system, a cross bar selector switch, a plurality of trunk lines incoming to said switch, a plurality of groups of trunk lines outgoing from said switch, group and line selecting bars common to said incoming trunk lines, means including a register controlled over any incoming trunk line for actuating a group selecting bar, means controlled by the actuated bar for preparing test circuits for all the trunk lines in the selected group, means for closing all said test circuits simultaneously, means controlled over one of said test circuits for actuating a line selecting bar, and means for automatically connecting the incoming trunk line in use to the outgoing trunk line selected by the actuated selecting bars.

40. In an automatic telephone system, a cross bar selector switch, a plurality of trunk lines incoming to said switch, a plurality of groups of trunk lines outgoing from said switch, group and line selecting bars common to said incoming trunk lines, group and line magnets for operating said bars, respectively, means including a register controlled over any incoming trunk line for operating a group magnet, thereby actuating a group selecting bar, means controlled by the operated magnet for connecting the test conductors of the trunk lines of the group selected by the actuated group selecting bar to the line magnets, respectively, means for closing test circuits including all said line magnets and the test conductors connected thereto, whereby the energization of the line magnets connected to the test conductors of idle trunk lines is initiated, means for completing the energization of a single line magnet, and contacts on the energized line magnet for placing a test potential on the test conductor connected thereto.

41. In an automatic telephone system, a cross bar connector switch, tens and units bars in said switch for selecting called lines, tens and units magnets for actuating said bars, respectively, means for energizing a tens magnet and a units magnet to select a particular called line, contacts closed by the actuated tens bar, and a test circuit for the called line including said contacts and contacts operated by the energized units magnet independent of the actuated units bar.

42. In an automatic telephone system, a cross bar connector switch, tens and units selecting bars in said switch, tens and units magnets for actuating said bars, respectively, a third set of bars equal in number to said ten bars, means including one of said tens magnets and one of said units magnets for operating a tens bar and a units bar to select a particular called line, means whereby the energized tens magnet also actuates the bar in said third set which corresponds to the operated tens bar, and a test circuit for the called line including contacts closed by the actuated third set bar.

43. In an automatic telephone system, a cross

bar connector switch, a plurality of trunk lines incoming to said switch, lines accessible to said switch, means including contact sets common to all said trunk lines for completing test circuits for called lines, means including tens and units magnets selectively energized over any trunk line for closing certain of said contact sets to complete the test circuit of a particular called line, contact sets individual to the trunk line in use selected by the energized magnets, and means controlled over said last mentioned test circuit for automatically closing said last mentioned contact sets if the called line is idle.

44. In an automatic telephone system, a cross bar connector switch, a plurality of trunk lines incoming to said switch, tens and units magnets in said switch, means controlled over any calling trunk for operating a tens magnet and a units magnet, a test circuit for a particular called line completed by operation of said magnets, a plurality of talking paths to said called line selected by operation of said magnets, said talking paths being individual to said trunk lines, respectively, and each talking path including a pair of serially related contact sets in said switch, means for testing the called line over said test circuit, and means controlled by said testing means for operating one of said pairs of contact sets to close the talking path individual to the trunk line in use if the called line is idle when tested.

45. In an automatic telephone system, a cross bar connector switch, tens and units selecting bars in said switch, means for actuating a tens bar and a units bar to select a called line accessible to said switch, contact sets selected by the actuated bars for completing a connection to the called line, means for testing the called line over a test circuit excluding said contact sets and including a contact closed by the actuated tens bar, and means controlled by said testing means for closing said contact sets if the called line is idle when tested.

46. In an automatic telephone system, a cross bar connector switch, tens and units selecting bars in said switch, tens and units magnets for actuating said bars, respectively, means for operating a tens magnet and a units magnet to select a called line through the medium of the associated bars, contact sets selected by the actuated bars for extending a connection to the called line, a test circuit for the called line excluding said contact sets and including a contact closed by the actuated tens bar and a contact closed by the operated units magnet independent of the actuated units bar, means for testing the called line over said circuit, and means controlled by said testing means for closing said contact sets if the called line is idle when tested.

47. In an automatic telephone system, a cross bar connector switch, a plurality of trunk lines incoming to said switch, means for registering two digits transmitted over one of said trunk lines, tens and units selecting bars, means for actuating a tens bar and a units bar under control of said registering means, serially related contact sets in said switch selected by the actuated tens and units bars, respectively, means individual to the trunk line in use for closing the selected contact sets, and a line accessible to the connector to which the trunk line in use is extended by way of the said contact sets.

48. In an automatic telephone system, a cross bar connector switch, a plurality of trunk lines incoming to said switch, a control unit common

to said trunk lines, tens and units selecting bars, means in said control unit for registering a digit transmitted over a calling one of said trunk lines, means responsive to such registration for actuating one of said tens bars, means in said control unit for registering a second digit transmitted over the calling trunk line, means responsive to the registration of the second digit for actuating one of said units bars, contact sets in said switch selected by the actuated tens and units bars, means individual to the calling trunk line for closing the selected contact sets, and a called line to which the calling trunk line is extended by way of said contact sets.

49. In an automatic telephone system, a cross bar connector switch, a plurality of trunk lines incoming to said switch, a plurality of groups of lines outgoing from said switch, digit registering means common to said trunk lines, means responsive to the registration of a digit transmitted over a calling trunk line for selecting a group of said lines, means responsive to the registration of a second digit transmitted over the calling trunk line for selecting a particular line in the selected group, a group of primary contact sets in said switch identified with the selected group, a secondary contact set in said switch identified with the selected line in said group, means individual to the calling trunk for actuating all said contact sets, and connections between the primary contact set associated with the selected line and said secondary contact set whereby the calling trunk line is extended to the selected line by actuation of said contact sets.

50. In an automatic telephone system, a cross bar connector switch, a plurality of trunk lines incoming to said switch, tens and units selecting bars, a common control unit, means in said unit controlled over a calling one of said trunk lines for registering two digits in the number of a called line accessible to said switch, means responsive to the registration of said digits for actuating one of said tens bars and one of said units bars, contact sets selected by the actuated bars for extending a connection from the calling trunk line to the called line, means in said control unit for testing the called line, and means individual to the calling trunk controlled by said testing means to close said contact sets if the called line is idle when tested.

51. In an automatic telephone system, a cross bar connector switch, a plurality of trunk lines incoming to said switch, tens and units selecting bars, a common control unit, means in said unit controlled over a calling one of said trunk lines for registering two digits in the number of a called line accessible to said switch, means responsive to the registration of said digits for actuating one of said tens bars and one of said units bars, contact sets selected by the actuated bars for extending a connection from the calling trunk line to the called line, means in said control unit for testing the called line, means in said control unit for transmitting a busy signal over the calling trunk if the called line is busy when tested, and means controlled by said testing means for closing said contact sets if the called line is idle.

52. In an automatic telephone system, a cross bar connector switch, a control unit, a plurality of trunk lines incoming to said switch and normally terminating in said control unit, tens and units selecting bars in said switch common to said trunk lines, means in said control unit controlled over a calling one of said trunk lines for

registering two digits in the number of a called line accessible to said switch, means responsive to the registration of said digits for actuating one of said tens bars and one of said units bars, a battery feed unit, contact sets selected by the actuated bars for extending a connection from said battery feed unit to the called line, and means controlled from said control unit for closing said contact sets and for switching the calling trunk line from the control unit to the said battery feed unit.

53. In an automatic telephone system, a cross bar connector switch, a control unit, a plurality of trunk lines incoming to said switch and normally terminating in said control unit, tens and units selecting bars in said switch common to said trunk lines, means in said control unit controlled over a calling one of said trunk lines for registering two digits in the number of a called line accessible to said switch, means responsive to the registration of said digits for actuating one of said tens bars and one of said units bars, a battery feed unit, contact sets selected by the actuated bars for extending a connection from said battery feed unit to the called line, and means controlled from said control unit for closing said contact sets and for switching the calling trunk line from the control unit to the said battery feed unit, means in said battery feed unit for closing a ringing circuit over the called line, and means in said battery feed unit responsive to the answering of the call for opening said ringing circuit and for completing the talking circuit between the calling trunk line and the called line.

54. In an automatic telephone system, a cross bar switch, a control unit, a plurality of trunk lines incoming to said switch and normally terminating in said control unit, normally closed contacts connecting the test conductors of said trunk lines together, means in said control unit responsive to the seizure of one of said trunk lines for placing a busy potential on all of said test conductors, digit registering means in said control unit controlled over the seized trunk line, tens and units selecting bars in said switch common to all said trunk lines, means responsive to the operation of said registering means for actuating a tens bar and a units bar, contact sets selected by the actuated bars for extending a connection from the seized trunk line to a line outgoing from the switch, other contact sets simultaneously selected by the actuated bars for extending connections from the other trunk lines to said outgoing line, means controlled from said control unit for opening said normally closed contacts, and means responsive to the opening of one of said normally closed contacts for closing only said first mentioned contact sets, whereby the seized trunk line is connected to said outgoing line to the exclusion of the other trunk lines.

55. In an automatic telephone system, a cross bar switch, a plurality of trunk lines incoming to said switch, said trunk lines being divided into groups, control units individual to said groups, respectively, line selecting devices in said switch controllable by said control units in succession, line connecting devices individual to said trunk lines, respectively, for establishing connections to lines selected by said selecting devices, and means in each control unit for controlling the operation of the connecting devices individual to the trunk lines of the group to which such control unit is individual.
